PRINTING CALCULATING APPARATUS SWITCH MEANS

Donald L. Rolph and Robert A. McKee, Hayward, Calif.,
assignors to Friden, Inc., a corporation of California

Application February 28, 1955, Serial No. 490,770

14 Claims. (Cl. 235—60.12)

This invention relates to printing and calculating apparatus and more particularly to such apparatus comprising a printing and a calculating apparatus arranged in combination and operable to prepare invoices to customers.

The object of the invention is to provide an improved and accurately operating apparatus operable to print identifying information and items of charge on invoices, rapidly calculate the required charges and print the required amounts on the invoices.

A feature of the invention resides in an improved electromagnetically operable multiplier control unit for the calculator.

Another feature resides in a selecting mechanism control for the calculator.

Another feature resides in the system of control whereby the calculations are performed while notations and information not required to be calculated are being entered on the invoice.

Another feature resides in the readout means provided in the calculator.

Another feature resides in a commutator switch device.

In the drawings:

Fig. 1 is a top plan view of the printing and calculating apparatus constructed and arranged in accordance with the invention and comprising a typewriter operable to control the calculator, the typewriter being at times operable under the control of the calculator;

Fig. 2 is an enlarged view of a set of control keys provided in the typewriter of Fig. 1;

Fig. 3 is an enlarged top plan view of a portion of the typewriter shown in Fig. 1, and shows the commutator switch and the carriage portion of the typewriter;

Fig. 4 is an enlarged top plan view of the commutator switch;

Fig. 5 is an end view of the commutator switch;

Fig. 6 is a view in perspective of a portion of the carriage portion of the typewriter and with the operating member of the commutator switch supported thereon;

Fig. 7 is a side elevational view, partly in section, of the switch operating member shown in Fig. 6;

Fig. 8 is a view in perspective and partly in section of another form of operating member for the commutator switch;

Fig. 9 is a side view of the operating member shown in Fig. 8;

Fig. 10 is an enlarged plan view of an upper portion of the commutator switch;

Fig. 11 is a view in cross-section of the portion of the commutator switch shown in Fig. 10;

Fig. 12 is an enlarged plan view of a lower portion of the commutator switch;

Fig. 13 is an end elevational view, partly in section, of a portion of the commutator switch;

Fig. 13A is a view, partly in section, of a portion

2

of the commutator switch portion shown in Fig. 13 and taken on the line 13A—13A in Fig. 13;

Fig. 14 is a simplified wiring diagram of portions of the commutator switch, and the electromagnetic means provided in the Add Keyboard section of the calculator for selectively operating the calculator;

Fig. 15 is a continuation of the wiring diagram shown in Fig. 14 and shows a portion of the commutator switch, the electromagnetic means for operating the multiplier unit of the calculator and cam switches in the typewriter;

Fig. 16 is a schematic showing of the readout switches and portions of the commutator switch in the calculator apparatus, and in a circuit arrangement including the solenoids for operating the typewriter printing mechanism;

Fig. 17 is a continuation of the schematic shown in Fig. 16 and shows the counter dial switches of the calculator and a portion of the commutator switch;

Fig. 18 is a schematic showing of a rotary step switch in a control unit operable to control the operations of the typewriter and calculator in accordance with a predetermined program;

Fig. 19 is a schematic showing the function solenoids to control the usually manually operated functional control keys of the calculator;

Fig. 20 shows the order in which Figs. 14, 15, 16, 17, 18 and 19 should be arranged to facilitate tracing of the circuits through the various elements involved in the system; and

Figs. 21 and 22 show copies of sample invoices prepared by means of apparatus constructed and arranged in accordance with this invention.

It will be seen that the view presented in Fig. 21 is divided into columns providing for separation of the various portions of the information contained in the bill. For example, the first column starting from the left may be used to provide space for indications of the character of the item centered on the bill. The second column from the left, and which is subdivided, is used for receiving indications of the quantity of items contained in the charge. The third column, and which is also subdivided, provides spaces for indicating the price of the article listed. The fourth column provides a space in which a description or name of the article charged may be recorded. The fifth column, and which is subdivided, provides space for indicating the gross amount of the charge. The sixth column, suitably subdivided, may be used to indicate a discount or tax applicable to the item charged. The seventh column may be used to receive an indication of the final amount of the charge.

In preparing bills to customers and of the type shown in Figs. 21 and 22 and by use of the present invention, the information required to be shown on the bill is typed in its proper place by operation of the typewriter. The calculations, wherever required, are calculated by means of the calculator which can be conditioned to be controlled by means of the typewriter and, in turn, may be conditioned to control the typewriter to make the typewriter type amounts calculated in the calculator.

The typewriter, in accordance with this invention, is equipped with electrical switch elements which are operable to control various elements in the calculator to make the calculator operate to record amounts to be entered on the bill, calculate and make extensions of the items as required, calculate the discounts or taxes applicable to the various items, make adjustments of the amounts in accordance with the discounts or taxes applying thereto, and sum up the charges into subtotals and grand totals, as required, and make the typewriter record the totals on the bill.

The typewriter apparatus employed in this invention may be any suitable electrically operable typewriter having means that may be controlled from a remote point for operating the printing mechanism.

The calculator apparatus employed in this invention

other than the ADD and SUB control members in the calculating machine may also be controlled from the typewriter position by virtue of the provision in the typewriter of the following additional functional control keys:

may be a calculator constructed and arranged so that the selectively operable members for controlling the entering of values in the apparatus may be controlled from some point remote from the calculator apparatus. Calculators of the so-called desk type, may be modified to make them suitable for use in this invention. For example, the calculator may be constructed, in general along the lines of the Friden, Inc. calculator shown in the Friden owned patents: C. M. Friden et al., No. 2,399,917; C. M. Friden et al., No. 2,403,273; and A. B. Machado et al., No. 2,653,765, issued May 7, 1946, July 2, 1946 and September 29, 1953, respectively, and in the Gilman Plunkett application, Serial Number 401,780 filed January 4, 1954, entitled "Calculating Machine."

The calculator used in this invention may be modified in the manner shown in the Gilbert J. Spesock et al. application, Serial Number 412,042 filed February 23, 1954, and assigned to the same assignee as the present application, the selecting slides in the application, which are used in setting the values in the calculator, being selectively controlled in the extent of movement by means of electromagnetically operable stop means controlled by means of switches located in a remotely located typewriter.

In the present invention, remotely controlled means are provided to control the operation of a multiplier unit in the calculator apparatus. The control means for the multiplier apparatus is controlled through a control unit provided between the calculator apparatus and the typewriter apparatus, and a commutator switch unit is provided in the typewriter apparatus to control the operations of the control unit in accordance with a predetermined program and to insure typewriting of amounts in required columns in the invoice. Remotely controlled means also under control of the control unit are provided in the calculator apparatus to control the addition, subtraction and other calculating functions of the calculator apparatus. A plug board is provided in the control unit to facilitate the changing of the program of operation of the apparatus when required, and a functional control keyboard is provided in the typewriter to enable ready control of the calculator apparatus from the typewriter position.

When it is desired to enter values in the calculator apparatus, numeral keys in the typewriter are operated, and the numeral keys used in this operation perform the same function as the numeral keys commonly provided in typewriter machines, but are also arranged to control electrical switches operable to control the operation of selectively operable members in the calculator apparatus to cause the selectively operable members to prepare the calculator for the entering therein of the value represented by the operated numeral keys of the typewriter. If the amount to be entered in the calculator is to be stored therein or added to whatever value is already in the calculator, the ADD key in the typewriter position is operated to close a circuit to an electromagnetic device operable to control the operation of the ADD control member in the calculator. If the instant amount set up in the calculator is to be subtracted from a value already in the calculator, the SUB (subtract) control member in the typewriter is operated to close a circuit to an electromagnetic device operable to control the operation of the SUB control member in the calculator. Control members

5

the labels of which stand for Extension, Negative Extension, Discount, Tax, Counter Total, Total Clear, Non-add and Error, respectively.

The values calculated in the calculator are represented 15 therein by the positions of numeral wheels which are conventional in calculators of the character above mentioned. Electrical switches are operated by means of the numeral wheels and, in effect, prepare circuit connections representative of the values calculated in the calculator. The values represented in the electrical switches for the numeral wheels can be, in effect, read 20 out of the calculator and used to control the operation of electromagnetic devices operable to make the typewriter type the values calculated in the calculator. In typewriting the values on the invoice, the values must appear in predetermined columns and in putting information into the calculator the values should be entered in predetermined ordinal positions. For example, the units, 25 tens, hundreds, etc. positions, and the positioning of the information is controlled at the typewriter position by means of the usual tab keys provided on the typewriter, and by a commutator switch mounted on the typewriter.

The commutator switch comprises spaced contacts and 30 conductor strips and is mounted on the typewriter and used 35 as a switch control means between the dial switches of the calculator apparatus and the multiplier unit of the calculator apparatus and between the carriage tabulating means of the typewriter and the control unit in the printing and calculating apparatus units. Some of the conductor 40 strips above mentioned serve in the nature of collector rings in the commutator switch. The step switch energizing points in the control unit are programmed to place plus potential on the energizing slip ring conductor strips of the commutator switch, the carriage wiper contacts of 45 the commutator switch are arranged to move with the carriage of the typewriter in a predetermined order and operate to prepare circuits between the energized conductor strips and their respective spaced contacts, operating members of the commutator switch being carried on 50 the carriage of the typewriter while other portions of the switch are supported in a fixed position.

A control unit involving the rotary step switch and 55 multicontact relays is provided between the typewriter and the calculator to enable control of the calculator by the typewriter, and control of the typewriter by the calculator.

As shown in Fig. 1, the apparatus of this invention 60 comprises a typewriter 100, a calculator 200, a control unit 300 and a commutator switch 400, the latter of which is secured to the typewriter 100.

The typewriter 100, as shown in Fig. 1, comprises an 65 apertured casing 101, the usual manually operable set of letter character keys 102, the set of functional keys 103, the space bar 104 and the set of numeral keys 105. The movable carriage 106 is of the conventional type found in electrically operated typewriters of the general form shown.

Commutator switch

The commutator switch 400, as shown in Figs. 1 and 3, 70 comprises a casing 401 supported on the rear portion of the casing 101 of the typewriter 100, a recess 107 being formed in the casing 101 to accommodate the casing 401 of the commutator switch 400. The casing 401 may be secured in place in the recess 107 by screws or other

75

suitable fastening means, not shown. The position of the commutator switch 400 is rearwardly of the longitudinally movable carriage 106 of the typewriter 100 and slightly below the level of the top of the casing 101. Within the casing 401 of the commutator switch 400 are supported spaced contact supporting plates 402 and 403, shown in Fig. 5, and a set of contact supporting carriages 404, the number of carriages provided in the commutator switch 400 depending on the number of circuits required to be controlled thereby. In the present illustrated showing of the invention there are twelve carriages 404, and which are hereinafter separately identified as carriages 404, 405, 406, 407, 408, 409, 410, 411, 412, 413, 414 and 415, as shown in Figs. 3 and 4. The carriages 405 to 415, inclusive, are slidably supported on the contact supporting plate 402 and are operable to be moved back and forth across the plate 402, as required, to serve as movable electrical connecting means between contacts on the contact supporting plate 402 and contacts on the contact supporting plate 403, the contact supporting plates 402 and 403 being maintained in parallel spaced relation by means of the insulating spacers 417 and 418 supported on suitable screws or holds 419 and 420 which extend through the respective splay bars 421 and 422, respectively, and through the contact supporting plates 402 and 403. It will be seen that the splay bars 421 and 422 may be apertured and countersunk to accommodate the heads of the screws or bolts 419 and 420, as the case may be, and that the lower ends of the screws or bolts 419 and 420 may be in holding engagement with the contact supporting plate 403, the spacers 417 and 418 being disposed between the contact supporting plates 402 and 403 and being suitably apertured to accommodate the screws or bolts 419 and 420. The splay bars 421 and 422 serve as ramps, of which portions supported on the carriages are run to cam movable latch fingers to required positions.

The contact supporting plate 402, as shown in Figs. 4, 5, 10, 11 and 13, is an apertured plate 423 of insulating material in which are supported, as shown in Fig. 10, conductor strips 424(A1A), 425(A1B), 426(A2A), 427(A2B), 428(A3), 429(M1A), 430(M1B), 431(M2), 432(R1A), 433(R1B), 434(R2), 435(R3), 436(A2A TAB), 437(A2B TAB), 438(TAB), 439(TAB) and 440(TAB HOLD).

The contact supporting plate 402 may be constructed in the manner of a printed circuit in which the conductor strips are deposited on the insulating sheet material or inlaid in the insulating sheet.

The conductor strips in the contact supporting plate 402 are located along edge portions of elongated apertures 441 to 452, inclusive, formed in the insulating plate 423. The illustration of the contact supporting plate 402 in Fig. 10 is an under surface view of the contact supporting plate, the conductor strips being located on the under surface of the insulating plate in order that each conductor strip may be in slidable engagement with an inverted U-shaped conducting member 453 supported in a carriage, such, for example, as the carriage 415 as shown in Figs. 13 and 13A.

The contact supporting plate 403, as shown in Figs. 5, 12, 13 and 13A, is an apertured plate 454 of insulating material in which are supported in a required pattern, as shown in Fig. 12, conductor strips 455, 456, 457, 458, 459, 460, 461, 462, 463, 464, 465, 466, 467, 468, 469, 470, 471, 472, 473, 474, 475, 476, 477, 478, 480, 481, 482, 483, 484, 485, 486, 487, 488, 489, 490, 491 and 492. The conductor strips 455 to 492, inclusive, are engageable by pin-type wiper contacts supported in the carriages, such, for example, as the pin-type wiper contact 493 supported in the carriage 415, shown in Fig. 13. The pin-type wiper contact 493 is in electrical connection with a spring 494 which is in electrical connection with the inverted U-shaped conducting member 453, a flanged

portion 495 of which is maintained in frictional engagement with a conductor strip 435(R3) on the lower surface of the contact supporting plate 402. The inverted U-shaped conducting member 453 has a flange portion 495 on one of its leg members 496 and a like flange portion 497 on the other leg member 498. The leg members 496 and 498 are accommodated in slots 499 and 500, respectively, which are in communication with an aperture 501 formed in the central portion of a body 502 of insulating material, the body 502 being the main supporting structure in the carriage 415. The body 502 is a rectangular block of insulating material and has a reduced width upper portion 503 dimensioned to extend upwardly in an elongated aperture formed in the contact supporting plate 402, the top of the upper portion 503 being substantially flush with the upper surface of the contact supporting plate 402. The lower portion of the body 502 is wider than the aperture formed in the contact supporting plate 402 and extends in the form of relatively thick flanges 504 and 505 directly below and in underlapping condition with the under surface of the contact supporting plate 402. Recesses 506 and 507 are formed in the upper surfaces of the flanges 504 and 505 and are provided in communication with the aperture 501. The recesses 506 and 507 accommodate the flange portions 495 and 497 on the leg members 496 and 498, respectively, of the inverted U-shaped conducting member 453, the flange portions 495 and 497 of which are pressed upwardly against the under surface of the contact supporting plate 402 by virtue of the pressure of the spring 494 which is compressed between the upper closed end portion of the inverted U-shaped conducting member 453 and the upper end of the pin-type wiper contact 493, the lower end of which is pressed against the upper surface 35 of the contact supporting plate 403. At such points where a conductor strip extends along the lower edge of an elongated aperture in which the carriage rides, such, for example, as the elongated aperture 452 shown in Figs. 3, 4, 13 and 13A, for accommodation of the carriage 415, the upper surface of at least one of the flange portions 495 or 497 will be pressed against the conductor strip in electrical conducting relation. For example, as shown in Fig. 13A, the upper surface of the flange portion 495 of the inverted U-shaped conducting member 453 is pressed against the under surface of the conductor strip 435(R3) to maintain electrical contact therewith during the journey of the carriage 415 along the conductor strip 435, the path of movement being from left to right or right to left, as the case may be, in the contact supporting plate 402 shown in Fig. 4.

An apertured top plate 509 is secured to the upper surface of the body 502 by rivets 510 and 511, or other suitable fastening means, the head portions 512 of which may be accommodated in recesses 513 and 514 formed in the body 502. Upper ends of the fastening means 510 and 511 may be spun over or otherwise anchored in the respective recesses 515 and 516. Upwardly extending apertured ears 517 and 518 are provided on the reduced width end portions 519 and 520, respectively, of the plate 509. The apertured ears 517 and 518 provide supports for relatively large-headed rivets 521 and 522, respectively, on which the respective latch fingers 523 and 524 are pivotally supported, the latch fingers 523 and 524 being operable to releasably latch the carriage to a movable member 525 constructed and arranged, as shown in Fig. 13, to fit into a space 526 between the inner end portions 527 and 528 of the respective latch fingers 523 and 524.

The latch fingers 523 and 524 are spring-biased toward the positions shown in Fig. 13, by means of the springs 529 and 530, respectively, which are located between the latch fingers 523 and 524, respectively, and the top plate 509. Lugs 531 and 532, extending downwardly from the inner portions of the respective latch fingers 523 and 524, serve to maintain the springs 529 and 530

in place, upper ends of the springs 529 and 530 being disposed around the lugs 531 and 532, respectively. The lower ends of the springs 529 and 530 may be seated in the recesses 515 and 516, respectively, to help to maintain the springs 529 and 530 against undue displacement from the desired and effective positions. Outer ends of the latch fingers 523 and 524 extend outwardly beyond end portions of the body 502 and are formed into the nose portions 533 and 534, respectively, thereby presenting at each end of the carriage assembly, a nose portion suitable for riding up a splay type ramp bar when the carriage is moved into engagement with the ramp bar, such, for example, as the splay type ramp bars 421 and 422, shown in Figs. 4 and 5, and which extend across the paths of movement of the carriages 404, 405, 406, 407, 408, 409, 410, 411, 412, 413, 414, and 415, as the carriages move in the elongated apertures 441, 442, 443, 444, 445, 446, 447, 448, 449, 450, 451 and 452, which are formed in the contact supporting plate 402 and are of sufficient length to permit movement of the carriages entirely across the pattern of conductor strips shown as appearing on the upper surface of the contact supporting plate 403, the relative arrangements of the contact supporting plates 402 and 403 being such that the carriages will move across the contact supporting plate 403 from left to right or from right to left according to the direction of movement of the movable member 525, which may be carried on the carriage assembly of the typewriter 100, as shown in Figs. 1 and 3, in which brackets 546 and 547 are mounted on, and extend from ends of the carriage 106 and rearwardly of the carriage 106 of the typewriter 100. Secured to, and extending between the brackets 546 and 547, and in parallel spaced relation with the carriage 106, are spaced bars 548 and 549. The lower edges of the bars 548 and 549 are formed to provide in each bar a row of teeth 550, Figs. 6 and 7. The spacing and arrangement of the teeth 550 may be, for example, such as will conform to the tabulating controlling teeth provided in the typewriter. Adjustably supported across the spaced bars 548 and 549 are a plurality of switch operating bars, the number provided being determined by the number of tabulating switching operations in the control pattern desired. Three switch operating bars 551, 552 and 553 are shown, for example, in Figs. 1 and 3, and since the switch operating bars 551, 552 and 553 are of like construction, an explanation of one will suffice for an understanding of all. It will be understood, however, that the number of operating bars may be more or less than three.

The switch operating bar 551, shown in Figs. 1, 3, 6 and 7, comprises a relatively long bar member 554 operable to extend across and beyond the space between the spaced bars 548 and 549. Upwardly extending pins or lugs 555 and 556 are provided on the bar 554 to extend into space between the teeth 550 on the spaced bars 548 and 549, respectively. Spaced posts 557 and 558 are supported in, and extend upwardly from, the bar member 554 and are secured at the points 559 and 560 to a relatively small plate 561, the function of which is to serve as a backing plate for the helical springs 562 and 563, supported on the posts 557 and 558, respectively. The springs 562 and 563 have their lower ends in pressure engagement with the upper surface of an apertured clamp bar 564, which is movably supported on the spaced posts 557 and 558, and has a portion extending beneath, and engaged by, the lower ends of the springs 562 and 563, and has upwardly extending and curved end portions 565 and 566 extending over, and into engagement with, the upper surfaces of the spaced bars 548 and 549, respectively. The bar member 554 has spaced and downwardly extending tabs 567 and 568 operable to engage the inwardly directed ends of the latch fingers 523 and 524 and serve as the movable member 525.

The number of tabs provided on the switch operating

bars 551 to 553, inclusive, may be different in each case and the relative spacing of the tabs may be made in accordance with the requirements of a predetermined program. For example, in the switch operating bar 552 there may be four tabs, 569, 570, 571 and 572, instead of the two tabs 567 and 568 on the bar 554 in the switch operating bar 551. It will be noticed that the tabs 569 and 570 in the switch operating bar 552 are relatively close together, the spacing being in accordance with the spacing between the elongated apertures 451 and 450 in the commutator switch 400 and therefore so that the tabs 569 and 570 will engage and move the carriages 414 and 413, respectively, when the carriage 106 of the typewriter 100 is moved sufficiently far to the left from the position shown in Fig. 3, to bring the tabs 569 and 570 to the left of the positions of the carriages 414 and 413 shown in Fig. 3. In this movement the carriages 410 and 407 will be engaged and moved to the left of the position shown in Fig. 3 by the tabs 571 and 572, respectively, on the switch operating bar 552.

On the switch operating bar 553, three tabs 573, 574 and 575 are provided, and the spacings of the tabs 573, 574 and 575 are such that the tab 573 will operate to move the carriage 412, the tab 574 will operate to move the carriage 408 and the tab 575 will operate to move the carriage 406 when the carriage 106 of the typewriter 100 is operated to move to a sufficient extent and in the required direction.

The switch operating bars 551 to 553, inclusive, may be readily adjusted along the bars 548 and 549 to positions different from those shown in Figs. 1, 3, 6 and 7, simply by pressing downwardly on the plates 561 to release the studs or pins 555 and 556 from engagement in the teeth 550 and by sliding the switch operating bars 551 along the spaced bars 548 and 549 to the new position. Release of the pressure on the plate 561 will allow the springs 562 and 563 to move the bar members 554 upwardly to bring the studs or pins 555 and 556 into engagement with the teeth 550 to hold the switch operating bar 551 in the new position.

In Fig. 5, the movable carriage 415 is at the right-hand side of the commutator switch 400. In the position shown, the carriage 415 has been moved to the right as far as permissible and the latch finger 524 has moved out of the path of movement of the movable member 525 which may therefore continue to move toward the right to some predetermined final point of movement in that direction without stalling the typewriter 100. The release of the carriage 415 from the movable member 525 is accomplished by virtue of the splay type ramp bar 421 and the latch finger 524, the nose portion 534 having a receding sloping portion 576 which is operable against the upwardly sloping surface 577 of the splay type ramp bar 421, which operates to cam the nose portion 534 upwardly and therefore move the inner end portion of the latch finger 524 downwardly below the path of movement of the movable member 525 which is representative of any suitable movable member, such, for example, as one of the tabs 567 to 575, inclusive. Movement of the movable member 525 to the left of the position shown in the right-hand portion of Fig. 5, will result in movement of the carriage 415 in a left-hand direction until the nose portion 533 of the latch finger 523 with its receding sloping portion 578, comes into engagement with, and runs up on, the upwardly sloping surface 579 of the splay type ramp bar 422. The downward movements of the inner end portions of the latch fingers 523 and 524 is against the actions of the springs 529 and 530, respectively, which are constantly trying to keep the inner ends of the latch fingers 523 and 524 elevated to their highest permitted position, which are controlled by virtue of the shoulders 580 and 581 formed on the latch fingers 523 and 524, respectively, the shoulders 580 and 581 being operable to engage an adjacent end portion of the body

502 to limit greater upward movement of the inner end portions of the latch fingers 523 and 524.

As shown in Fig. 5, the carriage in the right-hand portion of the figure and carrying a wiper contact 493 of the switch 400, has been moved to its extreme right-hand position and the movable member 525 can proceed to move further to the right of the stopped position of the carriage. In the left-hand portion of Fig. 5, the carriage 414 has been moved across the contact supporting plates and to its final left-hand position, and the movable member 525 can move still further toward the left to permit full range movement of the carriage 106 of the typewriter 100.

Tubular conducting terminals are secured to the conductor strips on the contact supporting plates 402 and 403. For example, as shown in Figs. 4 and 5, tubular terminals 582, 583, 584, 585, 586, 587, 588, 589, 590, 591 and 592, extend through apertures in the right-hand side of the contact supporting plate 402 and are spun over as shown, for example, at 593 to secure the terminal in place, a shoulder, not shown, of the terminal being pressed against a conductor strip formed on the insulating plate 423. A portion of the terminal 592, for example, extends through the aperture 604 formed in the contact supporting plate 402 and, as shown in Fig. 10, at one end of the conductor strip 435(R3), and a shoulder, not shown, on the terminal is in electrical connection with the conductor strip 435(R3). A portion of the terminal 591 extends through the aperture 603 formed in the contact supporting plate 402, and, as shown, at one end of the conductor strip 434(R2). A portion of the terminal 590 extends through the aperture 602 in the plate 402 and is in electrical connection with the conductor strip 433(R1B). A portion of the terminal 582 extends through the aperture 594 in the plate 402 and is in electrical connection with the two electrically connected conductor strips 424(A1A) and 432(R1A). A portion of the terminal 589 extends through the aperture 601 in the plate 402 and is in electrical connection with the conductor strip 431(M2). A portion of the terminal 588 extends through the aperture 600 in the plate 402 and is in electrical connection with the conductor strip 430(M1B). A portion of the terminal 587 extends through the aperture 599 in the plate 402 and is in electrical connection with the conductor strip 429(M1A). A portion of the terminal 586 extends through the aperture 598 in the plate 402 and is in electrical connection with the conductor strip 428(A3). A portion of the terminal 585 extends through the aperture 597 in the plate 402 and is in electrical connection with the conductor strip 427(A2B). A portion of the terminal 584 extends through the aperture 596 in the plate 402 and is in electrical connection with the conductor strip 426(A2A). A portion of the terminal 583 extends through the aperture 595 in the plate 402 and is in electrical connection with the conductor strip 425(A1B). On the left-hand side of the contact supporting plate 402 are the tubular terminals 605, 606, 607 and 608. A portion of the terminal 605 extends through an aperture 609 in the plate 402 and is in electrical connection with the conductor strip 436(A2A TAB). A portion of the tubular terminal 606 extends through the aperture 610 in the plate 402 and is in electrical connection with the conductor strip 437(A2B TAB). A portion of the terminal 607 extends through the aperture 611 in the plate 402 and is in electrical connection with the electrically connected conductor strips 438(TAB) and 439(TAB). A portion of the terminal 608 extends through the aperture 612 in the plate 402 and is in electrical connection with the conductor strip 440(TAB HOLD). Conductor wires, such, for example, as the insulated conductor wires 613 and 614 are extended through, and electrically connected to, the tubular terminals 582 and 592, inclusive, and to the tubular terminals 605 and 608, inclusive.

Tubular terminals 615 to 652, inclusive, are secured

75

to the contact supporting plate 403 to provide terminals for the conductor strips supported on the insulating plate 454. For example, as shown in Fig. 5, the tubular terminals 644, 645, 646, 647, 648, 649, 650, 651 and 652 are visible since they are in the foreground of the group of tubular terminals supported in the contact supporting plate 403. A portion of each tubular terminal extends through an aperture in the plate 403 and into electrical connection with a conductor strip in the pattern of conductor strips shown in Fig. 12. The tubular terminal 644, for example, extends into electrical connection with the conductor strip 484, the terminal 645 extends into electrical connection with the conductor strip 485, the terminal 646 extends into electrical connection with the conductor strip 486, the terminal 647 into connection with the conductor strip 487, terminal 648 to conductor strip 488, terminal 649 to conductor strip 489, terminal 650 to strip 490, terminal 651 to strip 491 and terminal 652 to conductor strip 492. It will be understood that for each conductor strip on the contact supporting plate 403 there is a tubular terminal extending through the plate of insulating material and to the under side of the plate 454. Also that wires of an electrical system are entered as required in the tubular terminals and electrically connected to the tubular terminals.

The contact supporting plates 402 and 403 are relatively arranged so that the conductor strips 424 to 440, inclusive, extend above, and crosswise of, the pattern of conductor strips involving the conductor strips 455 to 492, inclusive. As the carriages 404 to 415 are moved lengthwise in the elongated apertures 441 to 452, inclusive, respectively, the wiper contacts 493 in the carriages successively make contact with the conductor strips lying in the path of movement of the wiper contacts and during the traveling of the carriages, the conductor strips on the contact supporting plate 402 serve in the nature of conducting slip rings in the commutator switch 400, the conductor strips on the contact supporting plate 402 being, at times, engaged by the conducting flange portions 495 or 497 of the inverted U-shaped conducting members 453, carried in the carriages and being in electrical connection with the wiper contacts 493.

In Figs. 8 and 9, an improved switch operating bar 653 is shown which may be used in place of the switch operating bars 551, 552 or 553. The switch operating bar 653 may be stamped out of sheet metal and made all in one piece, and comprises two spaced parallel arm portions 654 and 655 joined at one end by a web portion 656 having ear members 657, 658 and 659 extending rearwardly beyond the web portion 656. The forward portion of the bar 653 terminates in a handle portion 660 apertured at 661 to permit ready lifting of the upper portion 654 of the operating bar 653 relative to one of a pair of spaced bars 662 and 663 which would take the place of the spaced bars 548 and 549, respectively, shown in Figs. 6 and 7, and which have already been described as being secured to, and extending between the brackets, 546 and 547 and in parallel spaced relation with the carriage 106 of the typewriter. The spaced bar 662 has teeth 664 formed on its inner face 665 to provide teeth between which the ear 658 may be inserted to hold the inner end of the switch operating bar 653 against undue movement along the bar 662. The ear members 657 and 659 are so spaced that the ear 657 will engage the upper surface of the bar 662 and the ear 659 will engage the lower surface of the bar 662 when the ear 658 is inserted between the teeth formed on the inner surface of the bar 662. The arm portion 655 is provided at its outer end with an upwardly directed tab 666 separated from the main portion of the arm 655 by a recess 667. The tab 666 is operable to extend between teeth 668 formed in the under surface of the bar 663. Tabs 669 and 670 are formed on the lower edge of the arm 655 to engage the latch fingers 523 and 524 on a carriage in the same manner as the tabs 567 and 568, respectively, engage the latch

fingers in the carriages, as previously described. In its normal position a downwardly directed lug 671 on the under surface of the arm 654 extends below the level of the upper face of the bar 663. The arm 654, however, may be manually lifted relative to the arm 655 to bring the lug 671 above the top of the bar 663. The switch operating bar 653 may then be moved to bring the lug 671 across the upper face of the bar 663 and to withdraw the ear 658 from engagement with the teeth 664. The switch operating bar 653 may be set in a required position by thrusting the ear 658 between teeth 664 in the bar 662 and by inserting the tab 666 in teeth 668 in the bar 663 at the required position and by pressing downwardly and longitudinally on the upper arm portion 654 until the lug 671 snaps down below the upper surface of the bar 663. A wing portion 672 extending from the handle portion 660 and overlying the bar 663 prevents undue downward movement of the switch operating bar 653.

In the interest of economy in space and the showing of wires in the explanation and illustration of the invention some of the conductor strips appearing in the contact supporting plate 493, shown in Fig. 12, appear in a reverse position in the wiring schematic shown in the combination of Figs. 14, 15, 16, 17, 18 and 19. It will also be seen that parts of the conductor strip 465, shown in Fig. 12, appear in Figs. 14 and 16 as broken off parts in lines of spaced contacts.

THE CALCULATOR

Add keyboard control

The calculator 200, as shown in Fig. 1, comprises an Add Keyboard in which electromagnetic devices are arranged in horizontal and ordinal rows to take the place of the usual manually operable keys found in calculators of the so-called desk type. In each ordinal row there are the electromagnetic devices 201, 202, 203, 204, 205 and 206. By operation of an electromagnetic device operable to selectively condition the calculator to enter a digit in a low or high order value in the calculator and by operating another electromagnetic device operable to selectively enter the required value of the digit and by operation of an electromagnetic device operable to set the calculator to add, the calculator may be operated to enter and indicate the value of the digit desired.

The electromagnetic devices 201 in each horizontal row will operate to prepare for a value of "4" or "9", the electromagnetic devices 202 in each horizontal row will operate to prepare to enter a value of "3" or "8", the electromagnetic devices 203 in each horizontal row will operate to enter a value of "2" or "7", and the electromagnetic devices 204 in each horizontal row will operate to enter a value of "1" or "6". The electromagnetic devices 205 in each horizontal row will operate to prepare to enter a digit of relatively low value such as "1" to "5" and operation of the electromagnetic devices 206 in each horizontal row will operate to prepare to enter a digit of relatively high value such as "6" to "9", inclusive.

Multiplier control

A group of solenoids 207 is provided to operate the otherwise manually operable number keys of the multiplier unit of the calculator 200. The electromagnetic devices for operating the number keys of the multiplier unit are located under an apertured plate member 208 mounted on the calculator 200, at the multiplier position, the plate member 208 being apertured to accommodate the plungers of the solenoids in the group 207. The number controlling solenoids in the group 207 are numbered "1" to "0", inclusive, and are shown in Fig. 15. Operation of these solenoids is equivalent to the manual operation of the corresponding number keys in the multiplier unit of the calculator. Supported also under the apertured plate 208 are solenoids 665, 209 and 210 which are operable to operate respectively the multiply key, mul-

tiply clear key and the negative multiply key of the multiplier unit. The plate 208 is provided with the apertures 211, 212 and 213 to accommodate the nonworking end portions of the solenoids 665, 209 and 210, respectively. A multiplier tab electromagnet 214, a 4/0 stop electromagnetic device 215, a pin set electromagnetic device 216, a CTR Entry electromagnetic device 217 and a CTR Nonentry electromagnetic device 218 are supported above the position of the apertured plate 208.

Functional keys for add keyboard

The usual manually operable Add Key, Subtract Key, Divd. Tab Key and Right-Hand Carriage Shift Key in the calculator apparatus are operable in the present invention by means of the solenoids 219, 220, 221 and 222, respectively, and operation of these solenoids is equivalent to the manual operation of the corresponding manually operable keys in the calculator 200. Also, included in the calculator 200 and shown in Fig. 19, are the electromagnetic devices 223 for the CTR NON-ACC operation, the electromagnetic device 224 for the L. H. CARR NON-ACC, and the electromagnetic device 225 for the ERROR P. B. RELEASE control.

Readout switches in calculator

Carriage dials.—In the calculator 200 the registering wheels supported in the carriage 226 and which are divided into two groups known as the carriage dials and the counter dials, are provided with rotary switches to set up electrical switching conditions representative of the values indicated by the registering wheels. The rotary switches 229 for the carriage dials are located beneath the line of circles shown at 227, while the rotary switches 230 for the counter dials are located beneath the position of the line of circles shown at 228. During the reading-out operation, the readout switches in the calculator 200 are successively read out and solenoids 231, shown in Fig. 16, and located in the typewriter 100, are operated to cause the typewriter to make a typewritten record of the amounts accumulated in the calculator and represented electrically by the condition of the readout switches. The carriage dials are arranged in the carriage 226 in ordinal positions to represent values in units, tens, hundreds, etc., and the number of ordinal places may be arbitrarily arranged and split into groups to represent, for example, half-cent values, whole-cent values and dollar values. As shown in Fig. 16, the carriage dials and the corresponding readout switches 229 are arranged in twenty ordinal positions. Position "1" indicates values of one cent, positions "2" to "6", inclusive, values of one-half cent, positions "7" to "13", inclusive, values in seven progressive ordinal positions. Positions "14" to "20", inclusive, are served by a portion of the commutator switch 400, different from the portions serving other parts of the carriage of the calculator, and, through the particular portion of the commutator switch, may control values and tabulating positions of the carriage.

Counter dials.—The counter dials in the calculator 200 are employed in this invention to represent quantity or control totals and the readout switches 230 of the counter dials are served by a portion of the commutator switch 400, different from the portions provided for serving the readout switches of the carriage dials. Each readout switch, like the readout switches for the carriage dials, comprises a set of ten circularly arranged fixed contacts and a wiper contact operable to successively engage the fixed contacts. The wiper contact is supported on a rotatable portion of the dial and is operable to move in accordance with the rotations of the dial and make contact with a fixed contact representing the position at which the dial stops at the end of each rotation.

Control unit.—The control unit 300, shown in Fig. 1, and provided between the typewriter 100 and the calculator 200, is operable to control the operations of the typewriter 100 and the calculator 200 in accordance with a predetermined program.

Included in the control unit 300 are a transformer 301, rectifier 302, resistor 303, a group of resistors 304, terminal blocks 305, the relays 306R₁, step relay 307R₂, tab relay 308R₃, zero omit relay 309R₄, multiply decimal relay 310R₅, multiplier entry relay 311R₆, restore relay 312R₇, control switches 313 and 314, toggle switches 315 and 316, a plug transfer board 317 and a step switch 318 with its stepping magnet 319, five banks of contacts comprising the homing bank 320, shown in Fig. 18, timing bank 321, energizing bank 322 and pulsing banks 323 and 324. The electrical devices above listed are suitably mounted on a board 325 along with the groups of rectifiers 326 and 327.

The apparatus may be supplied with power from a commercial source of current supply, not shown, through the extension cord, equipped with the plug 109. The source of commercial current supply may be utilized to operate the motor, not shown, but forming the driving power for the typewriter 100 as is common practice in the operation of electrical typewriters. The current supply, if of an alternating characteristic and relatively high voltage value, may be lead to, and suitably transformed and rectified, in the transformer 301, and the rectifier 302. Cables 328, 329 and 330 are provided as current carrying leads between the typewriter 100 and the control unit 300. Cable 331 extends between the electrical elements in the control unit and the plug board 17. Cables 332 and 333 provide electrical control lines between the calculator 200 and the control unit 300. The functional control keyboard 110, having the control keys shown in Fig. 2, is mounted on the typewriter 100 in a suitable manner and forms a manual keyboard means of controlling the operations of the calculating and typewriting apparatus. As indicated on the keys of the functional control keyboard 110, the apparatus may be controlled from the typewriter position to perform the calculating functions of adding, subtracting, figuring taxes, discounts, making extensions, negative extensions and figuring totals. Keys are also provided for nonadd operations and for correcting errors.

It will be understood that by suitable operation of the number keys in the standard typewriter keyboard, the typewriter 100 may be operated to make a typewritten record of the amount put into the typewriter and that automatically the same amount will be entered in the calculator 200. Also, that a plurality of amounts typewritten by the typewriter 100 may be automatically entered in the calculator 200 and required calculations may be made in the calculator and the totals, or products, of the calculations will be registered on the registering wheels in the calculator.

Furthermore, that the totals or products obtained in the calculator are represented therein by the instant settings of electrical readout switches 229 and 230 representing, respectively, the values accumulated in the calculator, and that the values represented electrically by the instant setting of the electrical switches can be read out through an electrical system in which solenoids 231 in the typewriter 100 are operable to control movement of the type characters in making a typewritten record of the values accumulated in the calculator 200.

Entry to add keyboard

Input to the Add Keyboard is accomplished by using a preselected energizing slip ring in the commutator switch 400 to complete a positive potential circuit to the Add Keyboard electromagnetic devices operable to release the selecting slides for movement in the calculator and to determine the extent of movement of the selecting slides to condition the calculator for entering therein of the required value. The order of input is preprogrammed and connections are made to the correct commutator segment. The order of input decided upon depends upon desired capacities in the apparatus for making the anticipated entries and the position of decimal points. There are two selections in the commutator

switch 400 for entering amounts in the Add Keyboard and the selections may be made by applying plus potential to the conductor strips 426(A2A) and 427(A2B) according to the manner selected. The plus potential is applied from a selected point on the rotary step switch energizing bank 322. Assuming that the conductor strip 427(A2B) is selected, the wiper contacts of the carriage 406 will make contact successively with the conductor strips 455 to 464, inclusive. Assuming that the amount should be entered in the tenth order place and that the number "9" key in the typewriter keyboard is operated, the circuit would be completed for placing a plus potential on the tenth order bus conductor 298, thus placing a plus potential on one side of all the Add Keyboard electromagnets in the tenth order. Depressing of the number "9" key in the typewriter would close the number "9" cam switch in the cam switches 199. The circuit for operation of the electromagnetic device 234 in the tenth position in the Add Keyboard in the calculator 200 through operation of the number "9" key in the typewriter 100, may be traced through Figs. 14, 15 and 18 as follows: In Fig. 18, plus conductor 333, conductor 334, conductor 335, movable contact 336 and upper contact 337 of the home multicontact relay 306 (R₁), conductor 338, closed contacts of carriage return switch 339, conductor 340, closed contacts of the cycle switch 232 in the calculator 200, closed contacts 341 in the restore relay 312 (R₇), conductor 342, conductor 343, energizing wiper 344 for the energizing bank of contacts 322 of step switch 318, contact 2 of the bank of contacts 322, movable contact 345, conductor 346 into cable 347, conductor 346 out of cable 347, in Fig. 14, conductor strip 426(A2A) of commutator switch 400, the inverted U-shaped member 453 and wiper contact pin 493 of wiper contact 675 of carriage 406, conductor strip 464, bus conductor 298, conductor 299, diode 233, winding of electromagnetic device 234, conductor 235, conductor 236, in Fig. 15, contacts 237, 238 and movable contact 239 of the number "9" cam switch of the cam switches 199 in the typewriter 100, bus conductor 240, cam ribbon switch 112, closed by the key lever arm in the typewriter 100, conductor 348, conductor 349, closed tab switch 350, closed shift lock switch 351, conductor 352 to conductor 353 which is connected to the minus side of the source of current supply, not shown. Energization of the electromagnetic device 234 will operate to release a latch in the calculator 200 to permit a high order selecting slide to move, the extent of movement being under the control of an electromagnetic device 241 which is operated to release a stop to extend into the path of movement of the selecting slide when the number "9" switch in the cam switches 199 is operated. The circuit for operation of the electromagnetic device 241 may be traced as follows: In Fig. 18, plus conductor 333, conductor 334, conductor 335, movable contact 336 and upper contact 337 of the home multicontact relay 306(R₁), conductor 338, closed contacts of carriage return switch 339, conductor 340, closed contacts of the cycle switch 232, closed contacts 341 in the restore relay 312(R₇), conductor 342, conductor 343, wiper 344 of the energizing bank of contacts 322 in the step switch 318, contact 2 of the bank of contacts 322, movable contact 345, conductor 346 into cable 347, conductor 346 out of cable 347, conductor strip 426(A2A) of commutator switch 400, the inverted U-shaped member 453 and wiper contact 493 of carriage 406, conductor strip 464, bus conductor 298, conductor 242, diode 243, winding of electromagnetic device 241, conductor 244, conductor 245, in Fig. 15, lower contact 246 and movable contact 247 of multiplier entry relay 311 (R₆), conductor 248, contact 238 and movable contact 239 of the number "9" cam switch of the typewriter 100, bus conductor 240, closed contacts of the cam ribbon switch 112, Fig. 18, conductor 348, conductor 349, closed tab switch 350, conductor 354, closed shift

lock switch 351, conductor 352 to conductor 353 which is connected to the minus side of the source of current supply, not shown.

By operation of the electromagnetic devices 234 and 241 the calculator 200 has been automatically operated from the typewriter position equivalent to the manual operation of the usual number "9" key in an ordinal position in the usually provided keyboard in a calculating machine. The electromagnetic devices 234 and 241 in the circuits above traced are in the tenth ordinal position in the Add Keyboard of the calculator 200. The electromagnetic device 234 is considered the high electromagnet in the ordinal position as compared with the electromagnetic device 249 positioned below it. The electromagnetic device 249 is operable to release the low order selector slide in the calculator for movement, the extent of which is controlled by one of the electromagnetic devices in the number position, such for example, as the electromagnetic device 241. If the low order electromagnetic device 249 is operated while the electromagnetic device 241 is operated, the low order selector slide will be operated instead of the high order selector slide, since the latch on the low order selector slide is controlled by the electromagnetic device 249, while the latch on the high order selector slide is controlled by the electromagnetic device 234. The electromagnetic device 241 controls the extent of movement of either the high order or the low order selector slide, whichever one happens to be released. Operation of the electromagnetic devices 241 and 249 together will prepare the calculator to enter a value of "4". The circuit for operation of the electromagnetic device 241 has already been traced to the conductor 244 and proceeds from thence to lower contact 355 and movable contact 246 of switch R6D, conductor 356, contacts 292 and 291 of the number "4" cam switch and to conductor 240. The circuit for operation of the electromagnetic device 249 in the tenth ordinal position may be traced as follows: Plus conductor 333, conductor 334, conductor 335, movable contact 336 and upper contact 337 of the home multicontact relay 306(R₁), conductor 338, closed contacts of carriage return switch 339, conductor 340, closed contacts of the cycle switch 232 in the calculator 200, closed contacts 341 in the restore relay 312(R₇), conductor 342, conductor 343, energizing wiper contact 344 for the energizing bank of contacts 322 in the step switch 318, contact 2 of the bank of contacts 322, movable contact 345, conductor 346, into cable 347, conductor 346 out of cable 347, conductor strip 426(A2A) of commutator switch 400, the inverted U-shaped member 433 and wiper contact 493 of carriage 406, conductor strip 464, bus conductor 293, conductor 297, diode 296, winding of electromagnetic device 249, conductor 295, conductor 294, contacts 293, 292 and movable contact 291 of the number "4" cam switch in the typewriter 100, conductor 240, closed cam ribbon switch 112, conductor 348, conductor 349, closed tab switch 350, conductor 354, shift lock switch 351, conductor 352, conductor 353 to the negative side of the source of current supply, not shown.

In the same ordinal position as the electromagnetic device 241 are the electromagnetic devices 290, 291 and 292, each of which, in cooperation with the electromagnetic devices 234 or 249, will condition the calculator for the entering therein of a predetermined value. Energization of the electromagnetic device 290 will release a spring-operated bolt to control the extent of movement of the selector slide for the high or low number values of "1" or "6." The circuit for operation of the electromagnetic device for the value "1" may be traced as follows, starting with the conductor strip 464, conductor 298, conductor 289, diode 288, winding of electromagnetic device 290, conductor 287, lower contact 286 and movable contact 285 of multiplier entry relay 311(R_{6A}), conductor 284, contact 283 and movable contact 282 of

the number "1" cam switch, conductor 240, closed cam ribbon switch 112, conductor 348, conductor 349, tab switch 350, conductor 354, shift lock switch 351, conductor 352 to conductor 353 and the minus side of the source of current supply, not shown. For the value "6," the circuit from the conductor 287 would extend through conductor 281, lower contact 280 and movable contact 279 of multiplier entry relay 311(R₆), conductor 278, contact 277 and movable contact 276 of the number "6" cam switch in the typewriter 100, conductor 240 and through to the minus conductor 353 by way of the cam ribbon switch 112, conductor 348, conductor 349, tab switch 350, conductor 354, shift lock switch 351 and conductor 352.

15 Energization of the electromagnetic device 291 will release a spring-operated bolt to control the extent of movement of the selector slides for the high or low number values of "2" or "7." The circuit for operation of the electromagnetic device 291 for the value "2," and starting from the conductor 298, may be traced as follows: conductor 275, diode 274, winding of electromagnetic device 291, conductor 273, lower contact 272 and movable contact 271 of multiplier entry relay 311(R₆), conductor 270, contact 269 and movable contact 268 of the number "2" cam switch, conductor 240, cam ribbon switch 112, conductor 348, conductor 349, tab switch 350, conductor 354, shift lock switch 351, conductor 352 to conductor 353. The circuit for operation of the electromagnetic device 291 for the value "7," and starting from the conductor 298, may be traced as follows: conductor 275, diode 274, winding of electromagnetic device 291, conductor 273, conductor 250, lower contact 251 and movable contact 252 of multiplier entry relay 311(R₆), conductor 253, contact 254, and movable contact 255 of the number "7" cam switch in the typewriter 100, conductor 240, cam ribbon switch 112, conductor 348, conductor 349, tab switch 350, conductor 354, shift lock switch 351, conductor 352 to conductor 353.

30 Energization of the electromagnetic device 292 will release a spring-operated bolt to control the extent of movement of the selector slides for the high or low number values of "3" or "8." The circuit for operation of the electromagnetic device 292 for the value "3," and starting from the conductor 298, may be traced as follows: conductor 256, diode 257, winding of electromagnetic device 292, conductor 253, lower contact 259 and movable contact 260 of multiplier entry relay 311(R₆), conductor 261, contact 262 and movable contact 263 of the number "3" cam switch of the typewriter 100, conductor 240, cam ribbon switch 112, conductor 348, conductor 349, tab switch 350, conductor 354, shift lock switch 351, conductor 352 to conductor 353. The circuit for operation of the electromagnetic device 292 for the value "8," and starting from the conductor 298, may be traced as follows: conductor 256, diode 257, conductor 253, conductor 263, lower contact 264 and movable contact 265 of multiplier entry relay 311(R₆), conductor 266, contact 267 and movable contact 198 of the number "8" cam switch of the typewriter 100, conductor 240, cam ribbon switch 112, conductor 348, conductor 349, tab switch 350, conductor 354, shift lock switch 351, conductor 352 to conductor 353.

65 The electromagnetic device 249 for controlling the selector slides for the low order of numbers "1" to "5," inclusive, is energized over circuits extending through the typewriter cam switches 199 for the different values as follows: for the value "1" and assuming that the cam switch for the value "1" is closed, the circuit is completed from conductor 295, conductor 197, contact 196 closed against contact 283, movable contact 282, conductor 240, cam ribbon switch 112, conductor 348, conductor 349, tab switch 350, conductor 354, shift lock switch 351, conductor 352 to conductor 353. For the value "2" the circuit for operation of the electromagnetic device 249 would be by way of conductor 295,

conductor 195, contacts 194 and 269 of the number "2" cam switch to conductor 249. For the value "3" the circuit for operation of the electromagnetic device 249 would be by way of conductor 295, conductor 193, contact 192, contact 262 and movable contact 263 of the number "3" cam switch to conductor 240. For the value "5" the circuit for operation of the electromagnetic device 249 would be by way of conductor 295, contact 191, contact 190 and movable contact 189 of the number "5" cam switch in the typewriter 100 to conductor 240.

The electromagnetic device 234 for controlling the selector slides for the high order of numbers "6" to "9," inclusive, is energized over circuits extending through the typewriter cam switches 199 for the different values as follows: for the value "6" and assuming that the cam switch for the value "6" is closed, the circuit is completed from conductor 235, conductor 188, contacts 187, 277 and movable contact 276 of the number "6" cam switch to conductor 240 and through cam ribbon switch 112. For the value "7" the circuit for operation of the electromagnetic device 234 would be by way of conductor 235, conductor 236, conductor 186, contacts 185, 254 and movable contact 255 of the number "7" cam switch to conductor 240. For the value "8" the circuit for operation of the electromagnetic device 234 would be by way of conductor 235, conductor 236, conductor 184, contacts 183, 267 and movable contact 198 of the number "8" cam switch, to conductor 240.

In the ninth ordinal position in the Add Keyboard of the calculator 200, are electromagnetic devices 234-9, 249-9, 290-9, 291-9, 292-9 and 241-9, corresponding to the electromagnetic devices 234, 249, 290, 291, 292, 241, respectively, found in the tenth order position. The electromagnetic devices 234-9 and 249-9 are the high and low electromagnetic devices, respectively, and their functions are to operate to release the latch members on the high and low selector slides, respectively, in the ninth ordinal position, the selector slides being operable to move lengthwise for a distance permitted by bolt parts of the electromagnetic devices for the number values. For example, the electromagnetic device 290-9 controls extent of movement of the selector slides for the values "1" and "6," the electromagnetic device 291-9 controls extent of movement of the selector slides for the values "2" and "7," the electromagnetic device 292-9 controls for the values "3" and "8," the electromagnetic device 241-9 controls for the values "4" and "9." The electromagnetic devices 234-9, 249-9, 290-9, 291-9, 292-9 and 241-9 are operable to be energized by way of the bus conductor 298-9, which is in electrical connection with the conductor strip 463 in the commutator switch 400. It will be seen that when the commutator switch 400 is operated to move the wiper contact 493 to engage the conductor strip 463, a circuit is prepared for operation of a selected electromagnetic device in the ninth ordinal position. Assuming, for example, that the wiper contact 493 in the carriage 406 is on the conductor strip 463, and that the key for the value "1" has been operated in the typewriter 100 to cause the number "1" typewriter cam switch to close, the electromagnetic devices 290-9 and 249-9 will be energized to set up the value "1" typewriter cam switch to close, the electromagnetic device 290-9 and 249-9 will be energized to set up the value "1" in the ninth order of the Add Keyboard in the calculator 200.

The circuit for operation of the electromagnetic device 290-9 may be traced as follows: positive potential conductor 333, conductor 334, conductor 335, movable contact 336 and fixed contact 337 of the home relay 306(R₁), conductor 338, closed carriage return switch 339, conductor 340, closed cycle switch 232, closed contacts 341 of restore relay 312(R₇), conductor 342, conductor 343, energizing wiper contact 344 of step switch 318, the number "2" contact in the energizing bank 322, movable contact 345, the "\$" contact, conductor 346 into

cable 347, conductor 346 out of cable 347, conductor strip 426(A2A), the U-shaped contact 453, shown in Fig. 13, in the carriage 406, wiper contact 493, carriage 406, conductor strip 463, bus conductor 298-9, conductor 289-9, diode 288-9, winding of electromagnetic device 290-9, conductor 287, lower contact 286 and movable contact 285 of multiplier entry relay 311(R₆), conductor 284, contacts 283 and 282 of the number "1" typewriter cam switch, conductor 240, cam ribbon switch 112 (closed), conductor 348, conductor 349, tab switch 350, conductor 354, shift lock switch 351, conductor 352 to conductor 353.

The circuit for operation of the electromagnetic device 249-9 may be traced as follows: positive potential conductor 333, conductor 334, conductor 335, movable contact 336 and fixed contact 337 of the Home Relay 306(R₁), conductor 338, closed carriage return switch 339, conductor 340, closed cycle switch 232, closed contacts 341 of Restore Relay 312(R₇), conductor 342, conductor 343, energizing wiper contact 344 of step switch 318, the number "2" contact in the energizing bank 322, movable contact 345, the "\$" contact, conductor 346 into cable 347, conductor 346 out of cable 347, conductor strip 426, the U-shaped contact 453, shown in Fig. 13, in the carriage 406, wiper contact 493 in carriage 406, conductor strip 463, bus conductor 298-9, conductor 297-9, diode 296-9, winding of electromagnetic device 249-9, conductor 295, conductor 197, contacts 196, 283 and movable contact 282 of the number "1" typewriter cam switch, conductor 240, cam ribbon switch 112 (closed), conductor 348, conductor 349, tab switch 350, conductor 354, shift lock switch 351, conductor 352 to conductor 353.

In the eighth ordinal position in the Add Keyboard of the calculator 200 are electromagnetic devices 234-8, 249-8, 290-8, 291-8, 292-8 and 241-8, corresponding to the electromagnetic devices 234, 249, 290, 291, 292, 241, respectively, found in the tenth ordinal position. The electromagnetic devices 234-8 and 249-8 are the high and low electromagnetic devices, respectively, and their functions are to operate to release the latch members on the high and low selector slides in the eighth ordinal position, the selector slides being operable to move lengthwise for a distance permitted by bolt parts of the electromagnetic devices for the number values. For example, the electromagnetic device 290-8 controls the extent of movement of the selector slides for the values "1" and "6," the electromagnetic device 291-8 for the values "2" and "7," the electromagnetic device 292-8 for the values "3" and "8" and the electromagnetic device 241-8 for the values "4" and "9." The electromagnetic devices in the eighth ordinal position are energized over the bus conductor 298-8 which is in electrical connection with the conductor strip 462 of the commutator switch 400, the circuits being completed as required by the selective operation of the typewriter cam switches 199.

In the seventh ordinal position in the Add Keyboard of the calculator 200 are the electromagnetic devices 234-7, 249-7, 290-7, 291-7, 292-7 and 241-7 corresponding to the electromagnetic devices 234, 249, 290, 291, 292 and 241, respectively, found in the tenth ordinal position. The electromagnetic devices 234-7 and 249-7 are the high and low electromagnetic devices, respectively, and their functions are to control the latch members on the high and low selector slides in the seventh ordinal position. The electromagnetic devices 290-7, 291-7, 292-7 and 241-7 control the extent of movement of the selector slides in the seventh ordinal position for the values "1" and "6," "2" and "7," "3" and "8," "4" and "9," respectively. The electromagnetic devices in the seventh ordinal position in the Add Keyboard of the calculator 200 are operable to be energized over the bus conductor 298-7 which is in electrical connection with the conductor strip 461 in the commutator switch 400,

the circuits being completed as required by the selective operation of the typewriter cam switches 199.

In the sixth ordinal position in the Add Keyboard of the calculator 200 are the electromagnetic devices 234-6, 249-6, 290-6, 291-6, 292-6 and 241-6, corresponding to the electromagnetic devices 234, 249, 290, 291, 292 and 241, respectively, found in the tenth ordinal position. The electromagnetic devices 234-6 and 249-6 are the high and low electromagnetic devices, respectively, and their functions are to control the latch members on the high and low selector slides in the sixth ordinal position. The electromagnetic devices 290-6, 291-6, 292-6 and 241-6 control the extent of movement of the selector slides in the sixth ordinal position for the values "1" and "6", "2" and "7", "3" and "8", "4" and "9", respectively. The electromagnetic devices in the sixth ordinal position in the Add Keyboard of the calculator 200 are operable to be energized over the bus conductor 298-6 which is in electrical connection with the conductor strip 460 in the commutator switch 400, the circuits being completed by the selective operation of the typewriter cam switches 199.

In the fifth ordinal position in the Add Keyboard of the calculator 200 are the electromagnetic devices 234-5, 249-5, 290-5, 291-5, 292-5 and 241-5 corresponding to the electromagnetic devices 234, 249, 290, 291, 292 and 241, respectively, found in the tenth ordinal position. The electromagnetic devices 234-5 and 249-5 are the high and low electromagnetic devices, respectively. The electromagnetic devices 290-5, 291-5, 292-5 and 241-5 control the extent of movement of the selector slides in the fifth ordinal position for the values "1" and "6", "2" and "7", "3" and "8", "4" and "9", respectively. The electromagnetic devices in the fifth ordinal position in the Add Keyboard are operable to be energized over the bus conductor 298-5 which is in electrical connection with the conductor strip 459 in the commutator switch 400, the circuits being completed by the selective operation of the typewriter cam switches 199.

In the fourth ordinal position in the Add Keyboard are the electromagnetic devices 234-4, 249-4, 290-4, 291-4, 292-4 and 241-4 corresponding to the electromagnetic devices 234, 249, 290, 291, 292 and 241, respectively, found in the tenth ordinal position. The electromagnetic devices 234-4 and 249-4 are the high and low electromagnetic devices, respectively. The electromagnetic devices 290-4, 291-4, 292-4 and 241-4 control the extent of movement of the selector slides in the fourth ordinal position for the values "1" and "6", "2" and "7", "3" and "8", "4" and "9", respectively. The electromagnetic devices in the fourth ordinal position in the Add Keyboard are operable to be energized over the bus conductor 298-4 which is in electrical connection with the conductor strip 458 in the commutator switch 400, the circuits being completed by the selective operation of the typewriter cam switches 199.

In the third ordinal position in the Add Keyboard are the electromagnetic devices 234-3, 249-3, 290-3, 291-3, 292-3 and 241-3 corresponding to the electromagnetic devices 234, 249, 290, 291, 292 and 241, respectively, found in the tenth ordinal position. The electromagnetic devices 234-3 and 249-3 are the high and low electromagnetic devices, respectively. The electromagnetic devices 290-3, 291-3, 292-3 and 241-3 control the extent of movement of the selector slides in the third ordinal position for the values "1" and "6", "2" and "7", "3" and "8", "4" and "9", respectively. The electromagnetic devices in the third ordinal position in the Add Keyboard are operable to be energized over the bus conductor 298-3 which is in electrical connection with the conductor strip 457 in the commutator switch 400, the circuits being completed by the selective operation of the typewriter cam switches 199.

In the second ordinal position in the Add Keyboard are the electromagnetic devices 234-2, 249-2, 290-2, 75

291-2, 292-2 and 241-2 corresponding to the electromagnetic devices 234, 249, 290, 291, 292 and 241, respectively, found in the tenth ordinal position. The electromagnetic devices 234-2 and 249-2 are the high and low electromagnetic devices, respectively. The electromagnetic devices 290-2, 291-2, 292-2 and 241-2 control the extent of movement of the selector slides in the second ordinal position for the values "1" and "6", "2" and "7", "3" and "8", "4" and "9", respectively. The electromagnetic devices in the second ordinal position in the Add Keyboard are operable to be energized over the bus conductor 298-2 which is in electrical connection with the conductor strip 456 in the commutator switch 400, the circuits being completed by the selective operation of the typewriter cam switches 199.

In the first ordinal position in the Add Keyboard are the electromagnetic devices 234-1, 249-1, 290-1, 291-1, 292-1 and 241-1 corresponding to the electromagnetic devices 234, 249, 290, 291, 292 and 241, respectively, found in the tenth ordinal position. The electromagnetic devices 234-1 and 249-1 are the high and low electromagnetic devices, respectively. The electromagnetic devices 290-1, 291-1, 292-1 and 241-1, control the extent of movement of the selector slides in the first ordinal position for the values "1" and "6", "2" and "7", "3" and "8", "4" and "9", respectively. The electromagnetic devices in the first ordinal position in the Add Keyboard are operable to be energized over the bus conductor 298-1 which is in electrical connection with the conductor strip 455 in the commutator switch 400, the circuits being completed by the selective operation of the typewriter cam switches 199.

It will be understood that when number keys 105 in the typewriter 100, shown in Fig. 1, are operated, corresponding typewriter cam switches 199 are operated to complete circuits for operation of the corresponding electromagnetic devices in the Add Keyboard of the calculator 200. As the typewriter keys are operated and the carriage 106 of the typewriter is moved lengthwise, the brackets 546 and 547 are carried along by the carriage 106 to move the commutator switch operating bars 551, 552 and 553 relative to the commutator switch 400, the operating bars 551, 552 and 553 being operable to selectively engage and move the carriages 404 to 415, inclusive, across the casing 401 of the commutator switch 400. The switch-operating bar 551 may be provided with a sufficient number and arrangement of tabs, such as the tabs 567 and 568, to be operable to engage and move a plurality of carriages. The switch-operating bar 552 is provided with a different number and arrangement of tabs from the number and arrangement provided in the bar 551, and a still different number and arrangement of tabs are provided on the operating bar 553. The number and arrangement of the operating bars provided on the carriage supported bars 548 and 549 and the number and arrangement of the tabs on the operating bars will be dependent upon the number of carriages it is required to operate in the commutator switch 400 and the time and sequence of operation required in the operation of the commutator switch 400.

In Fig. 4, twelve carriages 404 to 415, inclusive, are shown, and each carriage carries a pin-type wiper contact to engage conductor strips on the contact supporting plate 403. Each carriage also carries an inverted U-shaped conductor member, for example, such as the inverted U-shaped conductor member 453, arranged to be carried along in the carriage 415 and in frictional engagement with a conductor strip or strips supported on the contact supporting plate 402. The inverted U-shaped member 453, shown in Fig. 13A, has a flange portion 495 in frictional engagement with the conductor strip 435(R₃), the other flange portion 497 being in engagement with only the insulating material in the contact supporting plate 402. It will be seen that, in some cases, the flange portions 495 and 497 of an inverted U-shaped conductor

member 453 are at times in frictional and electrical connection with individual conductor strips in the contact supporting plate 402. Since, as heretofore pointed out, the inverted U-shaped member in each carriage is in electrical connection with the pin-type wiper contact in that carriage, the two parts maintained in electrical connection form, in effect, a bridging wiper contact operable to form, for example, a conductor member operable to selectively and electrically connect spaced conductor strips to a conductor strip common to the plurality of spaced conductor strips. For example, as shown in Fig. 14, the wiper contact 673 is operable, through its respective contact-making parts 493 and 495, to selectively and electrically connect the conductor strips 455, 456, 457, 458, 459, 460 and 461 to the conductor strip 424(A1A). The wiper contact 674, with its contact-making parts 493 and 495, is operable to selectively and electrically connect the conductor strips 455, 456, 457, 458, 459, 460 and 461 to the conductor strip 425(A1B). The wiper contact 675, through its pin contact wiper 493 and its flange portion 495 of the U-shaped member 453, is operable to selectively and electrically connect the conductor strips 455, 456, 457, 458, 459, 460, 461, 462, 463 and 464 to the conductor strip 426(A2A). The wiper contact 675, through its pin contact wiper 493 and its flange portion 497 of the U-shaped member 453, is operable to selectively and electrically connect the conductor strips 455, 456, 457, 458, 459, 460, 461, 462, 463 and 464 to the conductor strip 426(A2B). Through its pin contact wiper 493 and its flange portion 497, the wiper contact 676 is operable to selectively and electrically connect the conductor strips 455, 456, 457, 458 and 459 to the conductor strip 437(A2B TAB). The wiper contact 677, through its pin contact wiper 493 and its flange portion 495, is operable to selectively and electrically connect the conductor strips 465, 458, 459, 460, 461, 462, 463 and 464 to the conductor strip 428(A3). The wiper contact 678, shown in Fig. 15, through its pin contact wiper 493 and its flange portion 497, is operable to selectively and electrically connect the conductor strip 468 and the conductor strip 431(M2). The flange portion 495 of the wiper contact 678 is operable to engage the conductor strip 439(TAB) at a required point in the travel of the carriage 412 across the casing 401. The wiper contact 679, through its pin contact wiper 493 and its flange portion 497, is operable to provide an electrical connection between the conductor strip 468 and the conductor strip 430(M1B) and at selected times between the conductor strips 466, 467 and the conductor strip 430(M1B). The wiper contact 680, through its pin contact wiper 493 and its flange portions 495 and 497, is operable to selectively form an electrical connection between the conductor strips 468, 466, 467, and the conductor strip 429(M1A).

As shown in Fig. 16, the wiper contact 681, through its pin contact wiper 493 and its flange portion 495, is operable to selectively form an electrical connection between the conductor strips 465, 477, 478, 471, 479, 480, 481, 482 and 483, and the conductor strip 434(R₂), and through the flange portion 497 to make contact with the conductor strip 440 (TAB Hold). The wiper contact 682, through its pin contact wiper 493 and its flange portion 495, is operable to selectively and electrically connect the conductor strips 476, 475, 474, 473, 472, 471, 470, 469 and 465 to the conductor strip 433(R1B). The wiper contact 683, through its pin contact wiper 493 and its flange portion 495, is operable to selectively and electrically connect the conductor strips 465, 469, 470, 471, 472, 473, 474, 475 and 476 to the conductor strip 432(R1A). The wiper contact 684, shown in Fig. 17, through its pin contact wiper 493 and its flange portion

495, is operable to selectively and electrically connect the conductor strips 492, 491, 490, 489, 488, 487, 486, 471, 485, 484, and 465 to the conductor strip 435(R₃).

As shown in Figs. 16 and 17, there is a selector switch 5 685 for each of the twenty carriage dials in the calculator. Each selector switch has ten value contact positions 686 and a wiper contact 687 to selectively engage the value contact positions. The counter dials are also provided with individual selector switches 688, each comprising 10 like those for the carriage dials, a set of ten fixed contacts 689 and a wiper contact 690 movable in accordance with rotations of the dial and operable to selectively engage the fixed contacts. The wiper contacts 687 for the selector switches 685 and the wiper contacts 15 690 for the selector switches 688, are individually connected by conductors to corresponding conductor strips in the commutator switch 400. The fixed contacts in each selector switch for the value positions 686 and 689 are connected in series with corresponding contacts in the 20 selector switches for the other carriage dials and the counter dials. The value "1" fixed contacts in the selector switches 685 and 688 are electrically connected by means of conductor 691 to the number "1" typewriter solenoid 701. The value "2" fixed contacts in the selector switches 685 and 688 are electrically connected by means of conductor 692 to the number "2" typewriter solenoid 702. The value "3" fixed contacts in the selector switches 685 and 688 are electrically connected by means of conductor 693 to the number "3" typewriter 25 solenoid 703. The value "4" fixed contacts in the selector switches 685 and 688 are electrically connected by means of conductor 694 to the number "4" typewriter solenoid 704. The value "5", "6", "7", "8" and "9" fixed contacts in the selector switches 685 and 688 are electrically connected to the number "5", "6", "7", "8" and "9" typewriter solenoids 705, 706, 707, 708 and 709, respectively, by means of the conductors 695, 696, 697, 698 and 699, respectively. The value "0" fixed contacts in the selector switches 685 and 688 are electrically connected 30 by means of conductor 700 to the movable contact 710 of the Zero Omit Relay 309(R₄) which controls the operation of the "0" value solenoid 711 in the typewriter 100. A space solenoid 712 and a period solenoid 713 are provided in the typewriter 100. The value solenoids 701 35 to 709, inclusive, in the typewriter 100, are provided to control the operation of the typewriter in typewriting the values "1" to "9", inclusive, and are operable to make the typewriter 100 typewrite these values, under the control of the carriage dial selector switches and the counter 40 dial selector switches. The period solenoid 713 is operable, under control of the commutator switch 400, to control the operations of the typewriter 100 in typewriting period indications at required points.

The space solenoid 712 is operable, under the control 45 of the commutator switch 400 and the Zero Omit Relay 309(R₄), to make the typewriter tabulate to provide required spaces in the typewritten material.

The number solenoids 207 in the multiplier unit are under the control of the commutator switch 400 and 50 the Multiplier Entry Relay 311(R₆), as well as being under the control of the typewriter cam switches 199, which are operated selectively in accordance with the operation of the number keys 105 in the typewriter 100. When a number key 105 in the typewriter 100 is selectively operated and the Multiplier Entry Relay 311(R₆) is energized, the solenoid 207, corresponding in number 55 to the number key 105, operated in the typewriter 100, is operated to press the corresponding number key in the multiplier unit of the calculator 200. The multiplier Entry Relay 311(R₆), in its energized condition, operates the switch contacts R6A, R6B, R6C, R6D, R6E, R6F, R6G and R6H, shown in Fig. 15. The common spring contacts 285, 271, 268, 246, 279, 252, 265 and 247 in the switches R6A to R6H, respectively, are normally 60 spring biased against the relatively arranged lower fixed 65 contacts. The contacts R6A to R6H are connected in series with the contacts 285, 271, 268, 246, 279, 252, 265 and 247, respectively, in the multiplier unit of the calculator 200. The contacts R6A to R6H are connected in series with the contacts 70 285, 271, 268, 246, 279, 252, 265 and 247, respectively, in the multiplier unit of the calculator 200. The contacts R6A to R6H are connected in series with the contacts 75 285, 271, 268, 246, 279, 252, 265 and 247, respectively, in the multiplier unit of the calculator 200.

contacts 286, 272, 259, 355, 280, 251, 264 and 246, and by operation of the Multiplier Entry Relay (R₆) are moved away from these fixed contacts and into engagement with the upper fixed contacts 357, 358, 359, 360, 361, 362, 363 and 364, respectively, which are in electrical connection with the conductors 365, 366, 367, 368, 369, 370, 371, 372 and 373, leading to the operating windings of the solenoids "1" to "9", respectively, of the set of solenoids 207 which may be selectively operated to press down the corresponding keys "1" to "9", not shown, but provided in, and forming standard parts of, the multiplier unit of the calculator 200. The circuits for operation of the solenoids "1" to "9", inclusive, of the set of solenoids 207 may be traced up to the commutator switch 400 as follows: conductor 333, conductor 334, conductor 335, movable contact 336 and upper contact 337 of the Home Relay 306(R₁), conductor 338, carriage return switch 339, conductor 340, cycle switch 232(FCS) of the calculator 200, contacts 341 of the Restore Relay 312(R₇), conductor 342, conductor 343, wiper contact 344 serving the energizing bank of the rotary step switch 318, the numbers "1", "4" or "19" contacts of the energizing bank, conductors 374, 375, 376 leading into cable 347, conductors 374, 375 and 376 leading out of cable 347, conductor strips 429, 430 or 431 of the commutator switch 400, the wiper contacts 678, 679 or 680 and the conductor strips 466, 467 or 468 of the commutator switch 400, conductor 377, rectifier 378 and conductor 379 to conductor 380 which is a common conductor for the solenoids 207. The conductor strip 466 is in electrical connection with the conductor 380 by way of the conductor 381. The conductor strip 467 is in electrical connection with the conductor 380 by way of the conductor 382, rectifier 383 and conductor 384. The circuit for operation of the number "1" solenoid in the group 207 is traceable from conductor 380, conductor 385, winding of the number "1" solenoid 207, conductor 365, contact 357 and movable contact 285 of contacts R6A of Multiplier Entry Relay 311(R₆), conductor 284, contacts 283 and 282 of the number "1" typewriter cam switch 199, conductor 240, cam ribbon switch 112 (closed), conductor 348, conductor 349, tab switch 350, conductor 354, shift lock switch 351, conductor 352 to conductor 353. For operation of the number "2" solenoid in the group 207, the circuit may be traced from conductor 380, conductor 386, winding of the number "2" solenoid, conductor 366, contact 358 and movable contact 271 of R6B, conductor 270, contacts 269 and 268 of the number "2" typewriter cam switch to conductor 240. For the operation of the number "3" solenoid in the group 207, the circuit may be traced from conductor 380, conductor 387, winding of the number "3" solenoid, conductor 367, contact 359 and movable contact 260 of R6C, conductor 261, contacts 262 and 263 of the number "3" typewriter cam switch to conductor 240. For operation of the number "4" solenoid in the group 207 of the multiplier unit the circuit may be traced from conductor 380, conductor 388, winding of the number "4" solenoid, conductor 368, contacts 360 and 246 of R6D, conductor 356, contacts 292 and 291 of the number "4" typewriter cam switch to conductor 240. For operation of the number "5" solenoid in the group 207 of the multiplier unit the circuit may be traced from conductor 380, conductor 389, winding of the number "5" solenoid, conductor 369, contacts 190 and 189 of the number "5" typewriter cam switch to conductor 240. For operation of the number "6" solenoid in the group 207 the circuit may be traced from the conductor 380, conductor 370, contacts 361 and 279 of R6E, conductor 278, contacts 277 and 276 of the number "6" typewriter cam switch to conductor 240. For the operation of the number "7" solenoid in the group 207 the circuit may be traced from the conductor 380, conductor 391, winding

of the number "7" solenoid, conductor 371, contacts 362 and 252 of R6F, conductor 253, contacts 254 and 255 of the number "7" typewriter cam switch to conductor 240. For the operation of the number "8" solenoid in the group 207 the circuit may be traced from the conductor 380, conductor 392, winding of the number "8" solenoid, conductor 372, contacts 363 and 265 of R6G, conductor 266, contacts 267 and 198 of the number "8" typewriter cam switch to conductor 240. For the operation of the number "9" solenoid in the group 207 the circuit may be traced from the conductor 380, conductor 393, winding of the number "9" solenoid, conductor 373, contacts 364 and 247 of R6H, conductor 248, contacts 238 and 239 of the number "9" typewriter cam switch to conductor 240. For the operation of the number "0" solenoid in the group 207 the circuit may be traced from the conductor 380, conductor 394, winding of the number "0" solenoid 207, conductor 395, contacts 396 and 397 of the number "0" typewriter cam switch to conductor 240.

When the wiper contacts 679 or 680 engage the conductor strip 467, and plus potential is applied to the conductor strip 467 and the Counter Total Switch 715 near the contact "15" in the energizing bank 322 of the rotary step switch 318 has its movable contact 716 on its upper contact 717, the plus potential passes over conductor 718 and backward into cable 347 and outward of the cable in the energizing bank 322 at about the number "15" level, to upper contact 717 and movable contact 716 of Counter Total Switch 715 to conductor 719, contacts 720 and 721 of Multiplier Dec. Relay 310(R5B), conductor 722, winding of Relay 310(R₅), conductor 723, contacts 724 and 725(R5A) of Multiplier Dec. Relay 310(R₅), cam ribbon switch 112, conductor 348, conductor 349, tab switch 350, conductor 354, shift lock switch 351, conductor 352 to conductor 353.

Assuming that the multiplicand has been entered in the Add Keyboard by operation of the required electromagnetic devices 234 or 249, and 290, 291, 292 or 241, and that the multiplier has been entered in the Multiplier Keyboard by operation of the required electromagnetic device or devices 207, and that the Extend (EXT) key 726 is depressed, the rotary step switch 318 will be brought into operation to step its wiper contacts around over its banks of fixed contacts to cycle the apparatus through the multiplication program required to take place at predetermined points in the journey of the carriage 106 of the typewriter 100 in its normal direction of travel during the typewriting of characters on a sheet.

The rotary step switch 318 is a conventional rotary step switch and is prepared and conditioned for each step movement by operation of its electromagnet 319, which, upon energization, pulls back a spring-operated pawl, which, upon release of the step switch coil 319, will advance the rotor of the step switch to move the wiper contacts of the step switch 318 one step over the banks of fixed contacts. The initial circuit for operation of the rotary step switch 318 may be traced as follows: conductor 333, conductor 334, wiper contact 727 at the number "26" bank level, the number "26" bank level contact, conductor 728, latched-down contact 729 near the number "1" level, contact 730, contact 731, momentarily movable contact 732 of Extension Switch 726, contact 733, conductor 734, conductor 735, rectifier 736, conductor 737, conductor 738, winding of step switch coil 319, conductor 739, conductor 740 to conductor 353. The step switch coil 319, upon energization, operates to pull back its spring-operated advancing pawl ready for advancement of the wiper contacts of the step switch 318. When the step switch coil 319 becomes de-energized, the spring-operated pawl moves the rotor to move the wiper contacts one step, which, in this case, would bring the wipers to the number "1" level.

Simultaneously with the closing of the Extension Switch 726, the Home Relay 306(R₁) is operated to close its

movable contact 741 of its switch contacts R1A against its make-before-break contact 742 to provide a holding circuit for itself. The initial energizing circuit for the Home Relay 306(R₁) extends, in this case, from conductor 734, conductor 743, the normally closed contacts 744 of the switch contacts R1A, conductor 745, conductor 746, winding of Home Relay 306(R₁), conductor 747, conductor 739, conductor 740 to conductor 353.

Home Relay 306(R₁), upon operation, locks up over its holding circuit which extends from contact 730 to conductor 748 and thence upward to movable contact 741 and make contact 742 of the switch contacts R1A, conductor 745, conductor 746, winding of Home Relay 306(R₁), conductor 747, conductor 739, conductor 740 to conductor 353. Operation of the Home Relay 306(R₁) also closes the normally open contacts 749 of the switch contacts R1B and completes a circuit for a second operation of the step switch 318 which may be traced from the conductor 748 as follows: movable contact 741, contact 742 of the make-before-break contacts 744, conductor 745, closed contacts 749 of the Home Relay (R₁), conductor 750, closed contacts 751 SS(C) of the step switch coil 319, conductor 738, winding of step switch coil 319, conductor 739, conductor 740 to conductor 353.

Operation of the tab key in the typewriter and the consequent closing of the tab switch 752 will bring into operation the tab relay 308(R₃) over a circuit extending from the tab conductor strip 438 in the commutator switch 400, over conductor 753, conductor 754, tab switch 752 (closed), conductor 755, winding of tab relay 308(R₃), conductor 756 to conductor 353. During a reading out operation of the higher portion of the carriage in the calculator 200, the tab relay 308(R₃) is automatically brought into energized condition over a circuit extending from the number "8" level of the energizing bank 322 of the step switch 318 and the discount or tax push button switch, conductor 757 into cable 347, conductor 757 out of cable 347 in Fig. 16, conductor strip 434(R₂), wiper contact 681, conductor strip 440, conductor 758, conductor 755, winding of tab relay 308(R₃), conductor 756 to conductor 353.

It will be understood that with the entering of a value in the calculator 200, the dials in the carriage of the calculator are operated to register the value contained in the calculator and that rotation of the dials to the value indicated is accompanied by the corresponding movement of a movable member of a switch to, in effect, indicate electrically the same value as shown by the dial. The switches in the calculator operating in accordance with the settings of the dials are subsequently switched into a circuit involving solenoids in the typewriter, and the typewriter solenoids are operated in accordance with the settings of the switches in the calculator so that the typewriter automatically makes a typewritten record of the value stored in the calculator. The switches operated in accordance with the operations of the dials in the calculator are therefore, in effect, read out and used to control the operations of the number printing mechanism in the typewriter. The reading out operation may be controlled through the commutator switch 400 so that the figures typewritten by the typewriter will appear in the required columns on an invoice or other business form sheet.

In preparing the invoice or other business report, the amounts typed in by means of the typewriter are typed in the required columns on the sheet, and the carriage of the typewriter is moved along in the usual tabbing manner to bring the required columns, or parts of the sheet, to the point required for obtaining the printed record of the type character instantly applied.

In preparing the invoice, decimal points may be placed where required by suitable operation of the apparatus, and zeros may be omitted when the zeros are of nonsignificant value.

A definite program is carried out in preparing the invoices or other business forms by use of the apparatus of

this invention. The program is controlled by means of the rotary step switch 318, the commutator type switch 400 and the manually operable control keys located at the typewriter position and some secondary switches provided in the typewriter 100 and the calculator 200.

Rotary step switch

The rotary step switch 318, shown in the drawings and found applicable for use in the electrical system involved, is a ten-level, 26-position per level rotary type automatic switch having an isolated rotary wiper for each level that makes contact with individual points as the step switch is actuated. In the operation of a step switch the wiper remains in contact with an individual point during the time the step switch operating coil is energized and it does not move off this point until the energizing coil becomes de-energized. The interrupter springs which are normally closed, are momentarily opened each time the step switch is energized. Pairs of normally open contacts in the step switch are momentarily closed each time the step switch operating coil is energized, and the rotor of the switch is moved.

One level 320 of the switch 318 is utilized as the homing bank for the switch. Its wiper contact 727 is normally connected to a plus potential by way of the conductor 759 and is operable to move in steps over the twenty-six fixed contacts of the homing bank 320 during a full-cycle operation of the step switch 318.

One level 321 is used for the timing bank, its wiper contact 760 being connected to the energizing coil 319 of the step switch 318 through the normally closed home relay contacts 761(R_{1-D}) of the home relay 306(R₁).

Another level of the rotary step switch 318, and identified as the energizing level and called the energizing bank 322, is used primarily to energize certain of the conductor strips provided in the commutator switch 400. The energizing wiper 344 of the energizing bank 322 has plus potential applied to it except during a restore cycle, homing cycle, carriage return or calculator machine cycle.

Two levels 323 and 324 of the step switch 318 are used as pulsing banks of the switch. The stationary contact points of these levels are connected to function magnets and solenoids in the system. The pulsing wipers 762 and 763 have plus potential on them only when the step switch energizing coil is operated to cock the switch preparatory to an advance movement of the wiper contacts. During this operation the pulsing contacts 764 and 765 will close, and plus potential will be applied to the associated wiper contacts through the normally closed carriage return contacts 339, and contacts 336 and 337 (R_{1-C}) of the Home Relay 306(R₁).

Restore circuits

The restore circuits are for the purpose of restoring selector wiper arms to "0" position. The restore switch 766, in Fig. 18, will be actuated on the last 90 degrees of the calculator cycle. The restore switch 766, in closing, brings about energization of the restore relay 312(R₇), which, in operating, closes its contacts 767(R₇) to provide a sealing path for the restore relay 312(R₇) through conductor 768 to conductor 340. The restore relay 312(R₇) closes contacts 769(R₇) to close the circuit for the restore magnets 770 and 771 connected in parallel and which are operable to restore the selecting slides in the Add Keyboard of the calculator 200.

The circuit for the operation of the restore magnets 770 and 771 may be traced as follows: conductor 333, conductor 334, conductor 772, contact 769(R₇) of restore relay 312(R₇), conductor 773, conductors 774 and 775, windings of electromagnetic devices 770 and 771 in parallel, conductors 776 and 777 in parallel, conductor 740 to conductor 353. The restore relay 312(R₇) is sealed in over a circuit involving conductor 740, conductor 776, conductor 778 and winding of restore relay 312(R₇), conductor 779, conductor 780, conductor 781, restore break-

er contacts 782, normally closed conductor 783, contacts 767(R₇) closed by operation of restore relay 312(R₇), conductor 784, conductor 768 to conductor 340 and carriage return switch 339. Upon operation of the restore magnets 770 and 771 and the restoration of the selecting slides in the calculator 200, the restore breaker contacts 782 are opened to open the sealing-in circuit of the restore relay 312(R₇).

As above mentioned, the rotary step switch 318 employed in the system described, is a ten-level, 26-position per level rotary type automatic switch. The overall circuit, shown in the combination of Figs. 14, 15, 16, 17, 18 and 19, uses only five levels, two for pulsing the function solenoids and magnets, one for energizing selected energizing conductor strips, one for timing the program and one for automatic homing of the step switch to the desired program.

On the five levels of the switch employed, positions "1" through "7" are for the extension and negative extension programs, "8" through "12" are for the discount and tax programs, "13" through "15" are for the add and subtract programs, "16" through "18" are for counter total programs, "19" through "23" are for total and clear programs, "24" through "26" are for the error program.

The program desired may be selectively set by operating a suitable function key in the set of keys 110, shown in Fig. 1, the key 726 being the control key for the extension program, the key 785 is for the negative extension program, key 786 for the discount program, key 787 for the tax program, key 788 for the add program, key 789 for the subtract program, key 790 for the counter total control program, key 791 the total clear key, key 792 the nonadd program key, and key 793 being the error key.

To automatically position the step switch wipers at the beginning of any desired program, the operator pushes the desired program push button or key. Assuming the program just finished left the homing wiper 727 on point "23," and the operator desired the apparatus to go through an extension program, the operator would push the extension key 726 to start the extension program.

The operator, upon releasing the extension key 726, will cause the opening of contacts 731, 732 and 733, but will leave the contacts 729 and 730 closed. The step switch 318 will become de-energized and move to point "24." The interrupter contacts 751 will close again and the step switch will be energized through the interrupter contacts 751, the home relay contacts 749(R_{1-B}), the switch contacts 742 and 741(R_{1-A}), the closed contacts 729 and 730 to the homing bus 728. The step switch actuating, opens the interrupter contacts 751 to drop the step switch and it moves another point. This cycle continues until the homing wiper 727 rests on point "1" and since the movable contact 729 is separated from contact 792, the step switch will stop in its stepping activity at this point. This open circuit will cause the home relay 306(R₁) to drop out, opening its contacts and circuits to the step switch coil 319.

If another program key is depressed, the home relay 306(R₁) is again energized and the step switch 318 automatically steps to seek the open circuit between the homing bus and the positioning bus which was created by depressing the program push button key.

The nonadd release magnet 795 will be energized each time the home relay 306(R₁) is energized, the nonadd release magnet 795 being energized through its own contacts 796, if the nonadd key 792 has been depressed. This nonadd release magnet 795 is used to automatically release the nonadd key 792 after each program. Assuming that the nonadd switch 796 has been operated to close its contacts, the circuit for operation of the nonadd release magnet 795 may be traced as follows: from the conductor 734, conductor 797, closed contacts 796, conductor 798, winding of nonadd

release magnet 795, conductor 799, conductor 739, conductor 740 to conductor 353.

Each time the home relay 306(R₁) operates, its contacts 336 and 337(R_{1-C}) are opened to open the circuit between the plus potential conductor 335 and conductor 338 to take the plus potential off the step switch wipers 344, 762 and 763, and energize the carriage return solenoid 800 over the circuit that may be traced as follows: conductor 333, conductor 334, conductor 335, movable contact 336 and lower contact 801 of the home relay 306(R₁), contacts (R_{1-C}), conductor 802, conductor 803, winding of carriage return solenoid 800, conductor 804, tab switch 350, conductor 354, shift lock switch 351, conductor 352 to conductor 353.

Tabbing circuits

When it is desired to automatically tab to the total column for a readout; tab after a readout has completed to another column; or a manual tab after a program operation, which will energize the step switch to the next program point, the tabbing may be accomplished as follows:

Automatic tabbing is accomplished by placing a plus potential from a selected energizing point onto the tab motor line. The tab solenoid 805 is energized through the normally closed contacts 806 of the tab relay 308(R₃), and the energizing circuit may be traced from the pulsing bank 323 of the step switch 318 as follows: conductor 807, closed contacts 806 of tab relay 308(R₃), conductor 808, winding of tab solenoid 805, conductor 809, conductor 810, tab switch 350, conductor 354, shift lock switch 351, conductor 352 to conductor 353. The typewriter is tabbed, the tab linkages actuating the tab switch 350 to open the circuit to the tab solenoid 805. Tab switch 752 is closed to apply the positive potential from the energizing point in the energizing bank 322 of the rotary step switch 318 through conductor 811, conductor 807, conductor 812, rectifier 813, conductor 814, conductor 754, tab switch contact 752, conductor 755, winding of tab relay 308(R₃), conductor 756 to conductor 353. Contacts 815 of tab relay 308(R_{3-A}) provide a holding circuit for the tab relay 308(R₃), which may be traced as follows: conductor 333, contacts 815 (R_{3-A}) of tab relay 308(R₃), conductor 816, conductor 754, contacts 752, conductor 755, winding of tab relay 308(R₃), conductor 756 to conductor 353. After the tab cycle is over, tab switch 752 opens to cause de-energization of the tab relay 308(R₃). The tab switch 350 closes so that the positive potential from the energized point will once more energize the tab solenoid 805. This cycle continues until the carriage has moved for entry into the total column. The energized point connected to the tab motor line is also connected to the energizing conductor strip 434(R₂) of the commutator type switch 400.

After readout through the conductor strip 432(R_{1-A}), during the extension discount program, and readout through the conductor strip 435(R₃) during the counter total program, it is desired to tab into the next column. When the readout is over, the end commutator segments 817 of conductor strip 465 associated with conductor strip 432(R_{1-A}), and segment 818 of conductor strip 465 associated with conductor 435(R₃), are used to energize the step relay 307(R₂), which, in turn, causes energization of the step switch coil 319. The energization of the step relay 307(R₂) in this case, takes place over a circuit which may be traced from conductor strip 465, conductor 819, winding of step relay 307(R₂), solenoid ribbon switch 820, conductor 833, conductor 349, tab switch 350, conductor 354, shift lock switch 351, conductor 352 to conductor 353. The step switch is energized and the pulsing contacts complete the circuit from the plus potential to the pulsing points which are connected to the tab motor line. The tab solenoid 805

is energized, the holding circuit for the step relay 307(R₂) is broken by tab switch 350. Tab relay 308(R₃) is energized through tab switch 752 and the tab relay contacts 815 will provide the holding circuit for the step switch coil through its timing points until the tab cycle has completed. Then the tab relay 308(R₃) is dropped out, the step switch then moves to the next point.

When the operator tabs manually out of the price, quantity and percent of discount-tax column, it is necessary to step the step switch to another point. Tab conductor strips 438 and 439 TAB, 436 A2A TAB and 437 A2B TAB, are energized from their respective energizing conductor strips 429 M1A and 431 M2 and 426 A2A and 427A2B, respectively, through the wiper contacts in their associated carriages in the commutator switch 400, after the carriage brushes reach the decimal point positions. The operator now tabbing will close tab switch 752 and the positive potential from one of these tab conductor strips will energize the tab relay 308(R₃) which will operate to close the tab relay contact 815 R3A and the tab relay contact 821(R3B). Plus potential will be supplied initially in this case to the step switch coil 319 by way of conductor 753 and contacts 815 and conductor 333 and contact 821(R3B) in the timing bank 321. The step switch will start to pull and will then be more fully energized through the tab relay contacts 821 of the tab relay 308(R₃), the plus potential coming directly through by way of the conductor 333 and to the contact 761 of the home relay 306(R₁)(R_{1-D}) to energize the step switch until completion of the tab cycle. The wiper contacts of the step switch then move on to the next point.

Zero omission circuit

The omission of nonsignificant zeros during readout from the calculator, that is to say, those to the left of a decimal and first digit, is accomplished by means of the zero omit relay 309(R₄). The zero omit relay 309(R₄) is a high impedance telephone relay, its contacts 710(R_{4-C}) complete the circuit from the zero readout common conductor 700 to the space solenoid 712 of the typewriter 100. During readout of the dials of the calculator 200, if the first dial reads "0," this space solenoid 712 is energized to move the typewriter carriage one space to the left. The "0" dials will continue to control the typewriter 100 to leave spaces until the first significant digit is reached or a decimal point position has been reached which energizes the period solenoid 713. The common minus potential bus conductor 827 of the number solenoids "0" through "9" of the typewriter 100 and the period solenoid 713 is connected to the normally closed contacts of the zero omit relay 309(R₄) by way of the conductor 828. In the de-energized condition of the zero omit relay 309(R₄) the solenoids "0" through "9" and the period solenoid of the typewriter 100, will be in series with the zero omit relay 309(R₄). The first dial readout of the calculator 200 as a digit "1" through "9" will cause energization of the respective number solenoid in series with the zero omit relay 309(R₄). The high impedance of the relay prevents the number solenoids from becoming energized enough to actuate their number keys, but will permit operation of the zero omit relay 309(R₄) which will operate to provide a sealing path through its own contacts 822 to plus potential through the circuit of protective resistor 823 and conductor 342, restore contacts 341 of restore relay 312(R₇), calculator cycle switch 232FCS, conductor 340, carriage return switch 339, conductor 338, contacts 337 and 336, conductor 335, conductor 334 to conductor 333. The contacts 822 of the zero omit relay 309(R₄) are a make-before-break type of contact in which the movable contact 824 makes with contact 825 before contact 825 breaks with contact 826, the arrangement being such that the sealing circuit for the zero omit relay 309(R₄) is completed before the energizing circuit from the solenoid

minus bus conductor 827 is broken. The protective resistor 823 is used to prevent a short circuit between the plus and minus potential when the zero omit relay 309(R₄) is energized.

5 After the zero omit relay 309(R₄) seals in through its contacts 822, the circuit from the solenoid minus bus conductor 827, continued through 828, is broken. The circuit is completed from the minus bus 827 to the solenoid ribbon switch 820 through the zero omit relay contacts 831(R_{4-B}), conductor 832, solenoid ribbon switch 820, conductor 833, conductor 349, tabulating switch 350, conductor 354, shift lock switch 351, conductor 352 to conductor 353.

10 Any dials read out as "0" will now print "0's" because the circuit is completed from the calculator zero bus conductor 700, movable contact 710 and upper contact 833 of the zero omit relay, contacts R_{4-C}, conductor 834, winding of zero solenoid 711, conductor 835, conductor 836, contacts 831 of zero omit relay 309(R_{4-B}), conductor 832, solenoid ribbon switch 820, conductor 833, conductor 349, tab switch 350, conductor 354, shift lock switch 351, conductor 352 to conductor 353.

15 The readout of a decimal point which will energize a period solenoid 713 will also operate the zero omit relay 309(R₄) to lock it in, allowing "0's" to print after a decimal point has been printed. The zero omit relay 309(R₄) will remain locked up until an operation takes place that will break the lock-in circuit.

Readout of dials of the calculator 200

20 Readout of the dials of the calculator 200 is accomplished by the use of ten-position rotary switches in which the switch wipers rotate with the movement of the dials. As the dials come to rest, the wiper contacts make contact, in each case, with one of the ten stationary contacts surrounding the wiper contact. The stationary contact in each case is connected to the corresponding readout digit bus conductor. The typewriter solenoids 231 are connected to their respective number bus conductors 691 to 699, inclusive, except the zero 700 which transfers either to the space or zero solenoid through operation of the zero omit relay 309(R₄).

25 For the readout of the dials 14 to 20, inclusive, plus potential is applied to the conductor strip 434(R₂) from the energizing bank 322 of the step switch 318 through the selected step switch point, for example, point 8 and switch 900. When the typewriter carriage moves into position for this readout, the carriage contacts in the commutator switch 400 complete the circuit between the conductor strip 434(R₂), the tab holder conductor strip 440, and the commutator conductor strip segments 465, 477, 478, 471, 479, 480, 481, 482 and 483, selectively. The first conductor strip segment engaged is 483 and is effective to produce reading out of the 20th dial. Plus potential is therefore applied to the wiper arm 687 of the 30 rotary switch in the 20th position to energize a digit bus leading from one of the selected positions "0" to "9," inclusive, when the dial in the calculator is at rest. The corresponding typewriter solenoid will, in turn, be energized to cause the typewriter to typewrite the selected number. The key for the selected type character in the typewriter is actuated and as the key comes forward, the ribbon raising linkage in the typewriter actuates the solenoid ribbon switch 820 to open the circuit on the minus side of the typewriter solenoids 231. The typewriter, in 35 printing the required character, is conditioned to move another space and as the commutator segment is no longer carrying current during the carriage move, the carriage wiper will not be breaking a flow of current. The carriage wiper will now be making contact with the next commutator segment, for example, 482, and when the solenoid ribbon switch 820 closes again as the key arm returns to the cradle of the typewriter, the minus circuit is complete to the typewriter solenoids again and the dial information will be read out for dial "19." This 40 continues for readout for dials "18," "17" and "16," and 45 46 47 48 49 50 51 52 53 54 55 56 57 58 59 60 61 62 63 64 65 66 67 68 69 70 71 72 73 74 75 76 77 78 79 80 81 82 83 84 85 86 87 88 89 90 91 92 93 94 95 96 97 98 99 100 101 102 103 104 105 106 107 108 109 110 111 112 113 114 115 116 117 118 119 120 121 122 123 124 125 126 127 128 129 130 131 132 133 134 135 136 137 138 139 140 141 142 143 144 145 146 147 148 149 150 151 152 153 154 155 156 157 158 159 160 161 162 163 164 165 166 167 168 169 170 171 172 173 174 175 176 177 178 179 180 181 182 183 184 185 186 187 188 189 190 191 192 193 194 195 196 197 198 199 200 201 202 203 204 205 206 207 208 209 210 211 212 213 214 215 216 217 218 219 220 221 222 223 224 225 226 227 228 229 230 231 232 233 234 235 236 237 238 239 240 241 242 243 244 245 246 247 248 249 250 251 252 253 254 255 256 257 258 259 260 261 262 263 264 265 266 267 268 269 270 271 272 273 274 275 276 277 278 279 280 281 282 283 284 285 286 287 288 289 290 291 292 293 294 295 296 297 298 299 300 301 302 303 304 305 306 307 308 309 310 311 312 313 314 315 316 317 318 319 320 321 322 323 324 325 326 327 328 329 330 331 332 333 334 335 336 337 338 339 340 341 342 343 344 345 346 347 348 349 350 351 352 353 354 355 356 357 358 359 360 361 362 363 364 365 366 367 368 369 370 371 372 373 374 375 376 377 378 379 380 381 382 383 384 385 386 387 388 389 390 391 392 393 394 395 396 397 398 399 400 401 402 403 404 405 406 407 408 409 410 411 412 413 414 415 416 417 418 419 420 421 422 423 424 425 426 427 428 429 430 431 432 433 434 435 436 437 438 439 440 441 442 443 444 445 446 447 448 449 450 451 452 453 454 455 456 457 458 459 460 461 462 463 464 465 466 467 468 469 470 471 472 473 474 475 476 477 478 479 480 481 482 483 484 485 486 487 488 489 490 491 492 493 494 495 496 497 498 499 500 501 502 503 504 505 506 507 508 509 510 511 512 513 514 515 516 517 518 519 520 521 522 523 524 525 526 527 528 529 530 531 532 533 534 535 536 537 538 539 540 541 542 543 544 545 546 547 548 549 550 551 552 553 554 555 556 557 558 559 560 561 562 563 564 565 566 567 568 569 570 571 572 573 574 575 576 577 578 579 580 581 582 583 584 585 586 587 588 589 580 590 591 592 593 594 595 596 597 598 599 600 601 602 603 604 605 606 607 608 609 610 611 612 613 614 615 616 617 618 619 610 620 621 622 623 624 625 626 627 628 629 620 630 631 632 633 634 635 636 637 638 639 630 640 641 642 643 644 645 646 647 648 649 640 650 651 652 653 654 655 656 657 658 659 650 660 661 662 663 664 665 666 667 668 669 660 670 671 672 673 674 675 676 677 678 679 670 680 681 682 683 684 685 686 687 688 689 680 690 691 692 693 694 695 696 697 698 699 700 701 702 703 704 705 706 707 708 709 700 710 711 712 713 714 715 716 717 718 719 710 720 721 722 723 724 725 726 727 728 729 720 730 731 732 733 734 735 736 737 738 739 730 740 741 742 743 744 745 746 747 748 749 740 750 751 752 753 754 755 756 757 758 759 750 760 761 762 763 764 765 766 767 768 769 760 770 771 772 773 774 775 776 777 778 779 770 780 781 782 783 784 785 786 787 788 789 780 790 791 792 793 794 795 796 797 798 799 790 800 801 802 803 804 805 806 807 808 809 800 810 811 812 813 814 815 816 817 818 819 810 820 821 822 823 824 825 826 827 828 829 820 830 831 832 833 834 835 836 837 838 839 830 840 841 842 843 844 845 846 847 848 849 840 850 851 852 853 854 855 856 857 858 859 850 860 861 862 863 864 865 866 867 868 869 860 870 871 872 873 874 875 876 877 878 879 870 880 881 882 883 884 885 886 887 888 889 880 890 891 892 893 894 895 896 897 898 899 890 900 901 902 903 904 905 906 907 908 909 900 910 911 912 913 914 915 916 917 918 919 910 920 921 922 923 924 925 926 927 928 929 920 930 931 932 933 934 935 936 937 938 939 930 940 941 942 943 944 945 946 947 948 949 940 950 951 952 953 954 955 956 957 958 959 950 960 961 962 963 964 965 966 967 968 969 960 970 971 972 973 974 975 976 977 978 979 970 980 981 982 983 984 985 986 987 988 989 980 990 991 992 993 994 995 996 997 998 999 990 1000

the next commutator segment 471 will cause energization of the period solenoid 713 by way of conductor 836, and the solenoid 713 will operate to put in the decimal point. The readout switch will then continue on to dial "15" conductor strip segment 478 and thence to the number "14" conductor strip segment 477. After reading out dial "14" the carriage wiper contact will come to rest on the last commutator conductor strip segment 465 to cause energization of the step relay 307(R₂) by way of conductor 837, conductor 838 and conductor 819 to winding of step relay 307(R₂) when the solenoid ribbon switch 820 closes.

Energizing the step relay 307(R₂) will close contacts 839(R_{2-A}), to put plus potential on the step switch coil 319 to energize the step switch 318. The step switch 318, in pulling, will cause energization of some function solenoid, such as the tab solenoid 805 or carriage return solenoid 800, which will drop the step switch out to move the wiper contacts of the step switch to another position.

Entry to add keyboard of the calculator

Input to the Add Keyboard is accomplished by using a preselected energizing conductor strip and commutator section in the commutator switch 400 to complete the positive potential circuit to the Add Keyboard electromagnetic devices 234, 249, 290, 291, 292 and 241 as required, the typewriter cam switches 199 being operable to complete the minus potential circuit. The order of input is preprogrammed and connections are made to the correct conductor strip segments of the commutator switch 400. The order of input may be changed depending upon desired capacities of decimal points. Plus potential is applied to the energizing conductor strip in the commutator switch 400 from a selected point on the step switch 318 energizing level 322. The carriage wiper in the commutator switch 400 will make contact with the conductor strip segments when the carriage of the typewriter reaches the correct column for entry into the Add Keyboard of the calculator 200. This plus potential will now be applied to the 10th order bus, placing a plus potential on one side of all the Add Keyboard magnets in the 10th order.

The operator operating the number keys of the typewriter 100 will cause actuation of the respective cam switches, and the cam switch, in closing, makes the selection by completing the circuit from the minus potential to the selected Add Keyboard magnets. Sequence of selection is as follows: Assuming the operator is entering "1" to the Add Keyboard in the 10th order, the carriage wiper contact completes the plus potential circuit when the carriage reaches the correct column and position, bringing its wiper contact into engagement with conductor strip 464. Depressing the "1" typewriter key actuates cam switch "1" closing the circuit between the cam switch common bus and the common bus of the "1" or "6" magnets through isolation rectifier 288. The contacts of cam switch "1" in the bank of cam switches 199 also complete the circuit from the key cam common bus 240 to the low bus 295. The "1" key lever arm travelling still further, closes cam ribbon switch 112 to place a minus potential on the key cam common bus over conductor 240. The 10th order low magnet 249 and the 10th order "1" to "6" magnet 290 have their plus and minus circuits closed and will therefore be energized to enter "1" in the Add Keyboard of the calculator 200. Even though all the other 10th order magnets had plus potential on them, only the above two magnets had their minus circuits closed in this case.

The carriage of the typewriter will now move to energize the next conductor strip commutator segment which places plus potential on the 9th order bus.

Readout of the dials in the calculator 200 and re-entry to the Add Keyboard can be accomplished by energizing a readout energizing conductor strip and com-

mutator section, and at the same time an Add Keyboard energizing conductor strip and commutator section. The carriage wiper contacts are placed to complete both circuits with the same carriage motion.

Counter entry and readout

The counter dials can be used for quantity total or a control total, i. e., accumulation of a series of totals. If the counter dials are used for quantity total, the counter entry magnet 217 is energized from a pulsing point in the bank 323 and over a conductor 840 before the price and quantity amounts are multiplied. During the multiplication operation, the quantity is entered in the counter dials.

If the counter dials are used for control total, the totals read out during each total and clear program are re-entered into the multiply keyboard. A pulsing point "1" or "19" energizes the counter entry magnet 217 and then a multiplication cycle is started by application of a pulse through the number "1" contact in the pulsing bank 324 to operate the multiply tab magnet 214 over conductors 880, 881, through switch 868 and by operation of multiplier magnet 665 over conductors 880, switch 868, conductors 885 and 871, to store the amount in the counter dials "1" to "9," inclusive, 230.

During the total clear programs the counter dials are cleared each time if the counter is being used for quantity total. If the counter is used for control total, the counter is cleared only after a counter total program.

When the operator is entering the quantity into the multiply keyboard, the circuit to the multiply solenoids is by way of the conductor strip 429 M1A and the typewriter cam switches 199. If a number key is depressed when the plus potential is being applied to the conductor strip 429 M1A from a step switch energizing point in the bank 322, and the carriage wiper contact is in position to make contact between the conductor strip 429 M1A and the conductor strip 468 or 466 and 467, the cam switch closing energizes the selected multiply keyboard solenoid 207. When the cam ribbon switch 112 is closed, minus potential is applied to the multiply D. C. relay 310(R₅) through contacts 725 and 724 of multiplier D. C. relay 310(R₅), and this relay locks up by closing its movable contact 841 against contact 724, and by closing its movable contact 842 against contact 721 the holding circuit being by way of conductor 353, conductor 843, holding resistor 844, movable contact 841, contact 724, conductor 723, winding of MULT. DEC. relay 310(R₅), conductor 722, contact 721, movable contact 842, conductor 845 to conductor 333. The MULT. DEC. relay 310(R₅), will remain locked in until a positive pulse is applied to the holding resistor 844 from a programmed step switch point number "16" in the pulsing bank 324, the pulsing point being connected by way of conductor 846 to one terminal of the holding resistor 844, the other terminal being connected by way of conductor 843 to conductor 353, the wiper 763 in the pulsing bank 324 of the step switch 318 being connectable to the positive potential source through the SS contacts 765 and conductor 847 to conductor 340. Application of the positive potential to the holding resistor 844, in this case, bring a plus potential on both sides of the MULT. DEC. relay 310(R₅) so that the relay will drop out.

When the operator desires to read out the counter dials, the counter total push button 790 is depressed. In operating the counter total push button 790 the contacts 848 and 849 are momentarily electrically connected by means of the movable contact 850, and the movable contact 851 is moved down and latched against the contact 852, the step switch 318 homes to the beginning of the program, plus potential is applied to the conductor strip 435(R₃) by way of the energizing bank 322, point "16", cable 347 and conductor 843. When the carriage of the typewriter is in position so that the carriage wiper contact 684 completes the circuit between the conductor strip

435(R₃) and the conductor strip commutator segments 818, 484, 485, 486, 487, 488, 489, 490, 491, 492, the readout bus conductors 691 and 699, inclusive, will be selectively energized and, in turn, result in selectively energizing the typewriter solenoids 701 to 709, inclusive. The carriage in the commutator switch moves with movement of the carriage of the typewriter and operates to read out the next counter dial in succession. When the carriage wiper contact reaches the 9th segment, the space solenoid is energized by way of segment 485, conductor 853, closed contacts 854, conductor 855, winding of space solenoid 712, conductor 855', conductor 832, contacts 820 of step relay 307(R₂), conductor 833, conductor 349, contacts 350, conductor 354, contacts 351 of shift lock switch, conductor 352 to conductor 353. When the wiper contact 684 reaches the 10th contact 484, the circuit circuit to the space solenoid 712 is by way of segmental contact 484 and conductor 856 to closed contacts 857 and conductor 855. If, in entering the quantity amount, the MULT. DEC. relay 310(R₅) has been locked in, the circuit will be completed between the 9th segment through contacts 858 and 859 to the 2nd counter dial, also between segment 484, the 10th segment, and the 1st counter dial by way of contacts 860 and 861 of the contacts of the MULT. DEC. relay 310(R_{5-C}). The 1st and 2nd dials are read out by way of the contacts 860 and 861, and the 2nd dials are read out by way of the contacts 858 and 859. However, if the MULT. DEC. relay 310(R₅) is not locked in to hold movable contacts 859 and 861 against contacts 858 and 860, respectively, arrival of the wiper contact 684 on the segmental contacts 485 and 484 will cause energization of the space solenoid 712 by way of conductor 855.

If the counter dials are used for control total, the counter switch contacts 858, 859, 854 and 860, 851 and 857 will be in their required positions when the conductor strip 435(R₃) is energized to start the readout, and the MULT. DEC. relay 310(R₅) will be pulled.

The use of this circuit is to make it possible to store quantity amounts and total them. If whole numbers only are used, it is not necessary to enter the two extra zeros.

Portions of the conductor strip segmental contact 471 are arranged in association with the conductor strips 440, tab hold 434(R₂), 432(R_{1-A}), and 435(R₃). When the wiper contacts 681, 683, 682 and 684 make contact with conductor strip segmental contact 471 and plus potential is applied to the conductor strips, the period solenoid 713 in the typewriter 100 is operated by way of conductor 836 to typewrite a decimal point in the required position.

Commutator switch unit

The commutator switch unit 400 is used for readout of the carriage dial switches and counter dial switches in the calculator 200. It is also used for entry of amounts to the Add Keyboard and entry of amounts to the Multiply Keyboard in the calculator 200.

The step switch 318 and its energizing points are pre-programmed to place plus potential on the energizing conductor strips in the commutator switch 400. The carriage wiper contacts in the commutator switch 400, and which move with the carriages in the commutator switch when the carriage of the typewriter is moved, will complete the circuits between the conductor strips, in the upper contact supporting plate of the switch and their respective conductor strip commutator segments in the lower contact supporting plate of the switch, and tab conductor strips. The carriage wiper contacts in the commutator switch 400 are preset to conform to the type of billing form used in the establishment where the apparatus of this invention is applied.

The carriages in the commutator switch 400 are moved back and forth across the switch under the drive of the carriage 106 of the typewriter 100 by virtue of the bars 551, 552 and 553 which are adjustably carried on bars 548 and 549 supported on brackets 546 and 547 on the

carriage 106. The carriages in the commutator switch 400 are unlatched from the bars 551, 552 and 553 at the end of each excursion across the switch by means of the splay strips 421 and 422 which extend across the path of movement of the carriages in the commutator switch and provide ramps, up which the latch fingers on the carriages run to cam the inner ends of the latch fingers out of the path of movement of the bars 551, 552 and 553.

Below is given the use of each conductor strip in the commutator switch 400:

- 10 M1A—Conductor strip 429—Enter the quantity into the multiply keyboard.
- R₃—Conductor strip 435—Counter readout when used either for quantity, total or control total.
- 15 A2A—Conductor strip 426—Enter the price when the price is given per each.
- A2B—Conductor strip 427—Enter the price when the price is given per Cwt.
- R1A—Conductor strip 432—Readout the right-hand carriage of the calculator.
- 20 A1A—Conductor strip 424—Re-entry of R1A amounts to the add keyboard to follow with line discount.
- M2—Conductor strip 431—Enter the discount or tax amount in percent.
- 25 R1B—Conductor strip 433—Readout the right-hand carriage of the calculator.
- A3—Conductor strip 428—Re-entry of R1B to the add keyboard to enter into the accumulator or left-hand carriage, also used to enter a fixed amount by the operator which can be added to or subtracted from the accumulated total.
- R2—Conductor strip 434—Readout of the accumulated total.
- 30 M1B—Conductor strip 430—Re-entry of the R2 readout into the multiply keyboard for control total accumulation.

Entry to multiply keyboard and automatic-multiply zero

The M1A—M1B and M2 conductor strips commutator sections 429, 430 and 431, respectively, are used for entry into the Multiply Keyboard. M1A and M1B are identical as they are used in two separate columns but perform the same kind of function. M1A is used to enter the quantity amount into the keyboard, while M1B is used to re-enter the accumulated total readout into the keyboard when the counter dials 230 are being used for control total. The M2 section is used for entering the percent of discount or tax when doing an extension discount or tax program. The differences between the M2 and M1A sections are that the M2 is designed for entry of four digits into the right of the decimal point and the "1" point will not energize the MULT. DEC. relay 310(R₅).

Assuming the operator is entering the quantity amount, plus potential is applied from an energizing point "1" of the step switch 318 to the M1A conductor strip 429 by way of the cable 347. When the carriage of the typewriter 100 is in position for entering into the quantity column, the carriage wipers in the commutator switch 400 complete the circuit between the energizing conductor strip 429 and the multiplier conductor strip 468 to place plus potential on the multiply solenoid common bus, conductor 377 through rectifier 378 and conductor 379 to bus conductor 380, which is common to the Multiply Keyboard solenoids 207. Plus potential is also supplied from the conductor strip 468 through conductor 862, rectifier 863, conductor 864, to the pin-set electromagnet solenoid 216, the circuit being completed to the minus potential by way of conductor 865 and conductor 240.

When the operator now depresses a number key in the typewriter 100, its respective cam switch 199 closes to complete the circuit between the selected multiply solenoid 207 and the key cam common bus 240. The key arm travelling still further, closes the cam ribbon switch 112 to place minus on the key cam common bus before energization of the pin-set electromagnet 216 and the

multiply solenoid 207 selected. A pin in the pin-set element of the calculator 200 is set for every operation of a multiply solenoid 207 to the left of the decimal point.

The pin-set electromagnet 216 and the pin-set assembly above the multiply selection segments, the 4/0 stop switch 866 and the 4/0 stop magnet 215, the multiply tab magnet 214 and the multiply tab switches are used in combination for the automatic insertion of zeros into the multiply selection unit. Above the multiply selection segments is a pin-stop assembly of ten pins, one for each segment, which moves with the multiply selection unit as the multiply keys are depressed. To the left of the pin-set assembly is the stop so spaced that if the multiply selection unit moves two spaces to the left, an entry of two numbers, the top of the left-hand pin will come to rest against the 4/0 stop, preventing further movement of the selection unit. However, upon entering numbers into the multiply keyboard by energizing multiply solenoids, the pin-set magnet is also energized each time a number is entered to the left of the decimal point which actuates an arm 1464 to push a pin down for each selection. The pins pushed down will pass onto the 4/0 stop after the decimal point position is passed on the commutator unit 400; the pin-set magnet 216 is no longer energized, being blocked by rectifier 863; however, two more multiply solenoids can be energized and the selection unit made to move two more places before the 4/0 stop makes contact with the top of a pin stop. The movement which results, due to the pin stop and a pin-making contact, is used to actuate the multiply tab switches 867 and 868. For a more complete disclosure and understanding of the pin-set arrangement, reference may be had to the David F. Rutland et al. application S. N. 377,823, filed September 1, 1953, entitled "Calculating Machine," and assigned to the same assignee of the present application.

If the operator is using only whole numbers in the quantity column it is unnecessary to enter the two "0's" after the decimal point position. Proceeding on with the program, a pulsing point of the step switch 318 will energize the multiply tab magnet 214 by way of conductor 869 after the price has been entered to the Add Keyboard in the calculator. The multiply tab magnet 214 will actuate an escapement release pawl which releases the selection unit. However, it will only move two positions before the pin stop and pin make contact. The movement actuates the multiply tab switches 867 and 868 to transfer the positive potential from the pulsing points to the multiplier solenoid 665 in the calculator 200 by way of the conductors 870 and 871 which will operate to make the calculator 200 go through a multiplying cycle of operation in the same manner as when a manually operated multiply key in the calculator 200 is manually depressed.

During the time that the pulse point is the source of positive potential from the pulsing bank of the step switch to the multiply solenoid 665, the step switch must remain energized until the multiplication cycle starts. The hold switch 872, which is normally closed, is used to provide the holding circuit for these two program points "2" and "9" in the pulsing bank 323, a switch 872 being connected by conductor 873 to the conductor 738 and by the conductors 874 to the conductor 875 which leads to the points "2" and "9" in the pulsing bank 323.

When the multiplier tab switches 867 and 868 close, the plus potential from the pulsing point can be transferred either to the negative multiply solenoid 210 or the multiply solenoid 665, by the multiplier complement switch 876 which is operable to transfer the plus potential to either the conductor 877 or the conductor 870. The conductor 877 leads to the winding of the negative multiplier solenoid 210, the conductor 870 being in electrical connection with the conductor 871 which leads to the multiplier solenoid 665. This is used for the discount extension program when doing line discount and the net amount is desired rather than the amount of discount.

The M2 conductor strip 431 section of the commutator switch 400 is used for entering percent of discount or tax to the Multiply Keyboard in doing line discount. The amount entered to the left of the decimal point represents percent, i. e., amount written as 1.25 is programmed to appear in the multiplication as 1.25% or .0125. The M2 commutator section is designed for four places to the right of the decimal point, therefore, when the M2 conductor strip 431 has plus potential on it from the energizing point, the 4/0 stop magnet 215 will also have plus applied to it through the 4/0 stop magnet switch 866. The initial closing of cam ribbon switch 112 will energize the 4/0 stop magnet 215 over a circuit extending from conductor strip 431, conductor 878, 4/0 switch 866, conductor 879, winding of stop magnet 215 4/0, conductor 880 to conductor 240, pulling the 4/0 stop above the line of travel of the pin stops and latching it mechanically. The 4/0 switch 866 is also actuated to open the circuit to the 4/0 stop magnet 215. When the multiply selector unit is now released it will travel the distance of four positions before the pin stop engages with a permanent fixed 4/0 stop.

Program description

The following is a general description of the programs that may be followed with the apparatus of this invention. In these description detail tracings of the circuits are not contained.

EXTEND AND NEGATIVE EXTEND PROGRAM: (QUANTITY $\times$ PRICE = NET AMOUNT)

The extend and negative extend programs are the same except that in the negative extension program the net amount is subtracted from the gross amount. It can be used for an entry of credit.

The operator depresses either the EXT or NEG EXT program push button, the step switch 318 cycles to point "1," the beginning of the extension program. Point "1" is energized and applies plus potential to the M1A conductor strip 429, when the typewriter carriage is in position for entry of the quantity amount. After entering the quantity the operator tabs, which energizes timing point "1" in the bank 321 to energize the step switch coil 319. Pulsing point "1" in the bank 324 provides a pulse over conductor 880, closed contacts of switch 868, conductor 881, conductor 869 to multiplier tab magnet 214, to conductor 831 to energize the multiplier tab magnet 214 to release the multiply selection unit. If the counter is being used for quantity total, the counter entry magnet 217 is also energized over pulsing point "1" in bank 323, and conductor 840 to counter entry magnet 217, and conductor 882 to conductor 883 to conductor 831. After the tab cycle is over, the step switch 318 moves to point "2."

On point "2," energization point "2" applies plus potential to the A2B conductor strip 427, or A2A conductor strip 426 through the "\$/¢" switch 345 in the energizing bank 322. The operator enters the price amount and tabs again, energizing timing point "2" to pull the step switch 319. Pulsing point "2" in the bank 324 applies energy to the multiply solenoid 665 by way of conductor 880, multiply tab switch 868, lower contact 884 thereof, conductor 885, to conductor 879, conductor 871, multiply solenoid 665, conductor 885 to conductor 831. Energization of the multiply solenoid 665 is operable to start the calculator 200 on a multiply cycle. After the tab cycle is over the step switch 318 moves its wiper contacts to point "3."

Points "3" and "4" will be automatically pulsed through by placing plus potentials from energizing points "3" and "4" to the step switch coil 319 through the extension discounts switch 886, which will extend the plus potential over conductor 887 to conductor 750, and the step switch interrupter contact 751. The step switch coil 319 is energized again on timing point "5" over conductors 888, 342, contacts 839(R₂-A) of step relay 307(R₂), con-

ductor 889 to conductor 739. On pulsing point "5" in the bank 323, the right shift solenoid 222 in the calculator 200 will be energized over conductors 889 and 890 to conductor 831, so that the right shift solenoid will be shifting the carriage of the calculator 200 to the right while the operator of the typewriter is typing descriptive information on the billing form. It is to be noted, however, that the plus potential to the timing wiper 760 is broken by the opening of the cycle switch 232FCS so that the energization of the step switch coil 319 and right shift solenoid 222 on point "5" will not take place until the multiplication cycle has been completed. Pulsing point "5" in the bank 324 will operate to carry plus potential to the counter nonentry solenoid 218 by way of conductor 891 to winding of counter nonentry magnet 218 which is connected by means of conductor 892 to conductor 883. After the shift right solenoid 222 operates, the cycle switch 232FCS opens to remove the plus potential from the timing point "5" in bank 321 of the step switch, causing de-energizing of the step switch as it comes to point "6."

On point "6" there will be plus potential when the shift right cycle is over and the cycle switch 232FCS closes again, which places plus potential on the R1B conductor strip 433 and the A3 conductor strip 428 through extension push button switch 893 in bank 322.

As soon as the carriage reaches the total column the readout of the carriage dial switches associated with conductor strip 433(R1B) will occur and also re-entry into the Add Keyboard through the conductor strip 428(A3) follows, the last segment of the contacts associated with the R1B conductor strip 433 will energize the step relay 307(R₂), which closes its contacts to cause energization of the step switch coil 319. When the wiper contact 763 is on pulsing point "6" in the bank 324, a potential will be applied to the plus or minus bus conductor 894 through a nonadd push button switch 792, which will, in turn, cause energization of the plus or minus solenoids 219 and 220, respectively, in the calculator, depending upon which program is operated, extend or negative extend, which may be controlled by suitable operation of the switches 895 and 785, respectively. The amount read out from the R1B conductor strip 433 portion of the calculator and re-entered into the Add Keyboard will be added to, or subtracted from, the accumulated or gross total in the left-hand portion of the carriage of the calculator 200. The plus or minus cycle will cause opening of the cycle switch 232FCS to remove the plus potential from the timing point "6." The step switch then moves to point "7." As soon as the plus or minus cycle is over, the cycle switch 232FCS closes to place plus potential on timing point "7," pulling the step switch coil 319. Pulsing point "7" in the bank 323 will supply plus potential to the home relay 306(R₁) by way of conductors 896, 897, 734, conductor 743, contacts 742 and 744 of home relay 306(R_{1-A}), conductor 745, conductor 746, winding of home relay 306(R₁), conductor 747, conductor 739 to conductor 740 and conductor 353. The home relay 306(R₁) seals in, opening the circuit applying plus potential to the step switch wipers and also the circuit between the step switch and timing wiper. The step switch will automatically home to the beginning of the extension program setting it up for another extension.

The step switch program has done the following: entered the quantity and the price—the two were multiplied together, the carriage of the calculator shifted right. The product of quantity times price has been read out from the dials of the calculator of the right-hand portion of the carriage and re-entered into the Add Keyboard. The plus or minus solenoid is energized to add to, or subtract from, the accumulated total in the left-hand carriage portion of the calculator 200.

DISCOUNT EXTENSION: (QUANTITY $\times$ PRICE = EXTENSION $\times$ DISCOUNT = NET TOTAL)

Discount extension is the same program as the extension program except two additional points are used in the discount extension program.

If the extension discount switch 886 had not been in the position shown in the bank 322, the step switch, in coming to points "3" and "4," would not have been pulsed through these points. The switch stopping on point "3" would cause reading out of the amount of quantity $\times$ price from the right-hand dials through the R1A conductor strip 432 and commutator section, and re-entering into the Add Keyboard by the A1A conductor strip 424 section of the commutator switch. The end commutator section 817, of the R1A portion of the commutator switch 400 is connected by means of conductor 898 to conductor 837, which is connected to conductor 838. When the wiper contact 682 engages the end segment 817 connected to conductor 898, the step relay 307(R₂) is operated. The pulsing point "3" of the bank 323 will energize the tab solenoid 805 through the tab relay contacts 806 of tab relay 308(R_{3-C}). The tab cycle will actuate the tab switch 752 to energize the tab relay 308(R₃), which will operate to open the circuit to the tab solenoid 805 and provide a holding circuit for the step switch 319 through contacts 821 of tab relay R3. Pulsing point "3" on bank 324 will energize the counter nonentry magnet 218 by way of conductor 891. After the tab cycle is over the tab switch 752 opens to drop out the tab relay 308(R₃), which, in turn, opens the holding circuit of the step switch coil 319 so that the step switch 318 will move its wipers to point "4."

Energizing point "4" in the bank 322 will apply plus potential to the M2 conductor strip 431.

The tab from point "3" is set to align the typewriter carriage for entry of the amount of line discount usually given as the decimal equivalent, which will go into the Multiply Keyboard of the calculator. The operator of the typewriter, in tabbing out of this column, will bring the step switch 318 into condition so that its wiper contacts will be on the number "4" position. Energizing the timing point "4" in the bank 321 will cause energization of the step switch coil 319. Pulsing point "4" in the bank 323 provides a holding circuit for the step switch coil 319 by way of conductors 874, 875, and the holding switch 872 in the calculator 200. Pulsing point "4" in the bank 324 energizes the multiply tab magnet 214 through extension discount switch 886, conductors 881 and 869, and the multiplier tab switch upper contacts 867. The multiply tab magnet 214 releases the multiply selection unit in the calculator which actuates the multiply tab switch 867 when the pin, set up in the pin-set unit in the calculator, engages with the 4/0 stop 215, armature arm 1439, which corresponds to the zero stop arm (439) shown in the aforementioned David F. Rutland et al. application S. N. 377,823. The actuating of the multiply tab switch 867 transfers the positive potential from pulsing point "4" in the bank 324 to the multiply COMP switch 876, which, when its movable contact is on the lower fixed contact, will carry energization to the negative multiplier solenoid 210 by way of the conductor 877. If line discount is being done and the net total is desired, the multiply cycle will actuate the holding switch 872 to open the step switch holding circuit, allowing the step switch to move its wiper contact to step "5." The remaining part of the extension program will be the same from point "5" until the step switch will automatically home to the beginning of the extension program as described under the heading "Extend and Negative Extend Program."

DISCOUNT OR TAX PROGRAM: (TOTAL $\times$ PERCENT DISCOUNT OR TAX = AMOUNT OF TAX OR DISCOUNT)

The discount and tax programs are the same except that in the tax program the amount of tax is added to the accumulated total, and the discount program subtracts

the amount of discount from the accumulated total.

When the discount or tax program is to be performed, the operator depresses the DISC manually operable switch 786 or the TAX manually operable switch 899 as required, to start the step switch 318, which automatically moves its wiper contacts to the "8" point position for the beginning of these programs.

Energizing point "8" in the bank 322 will place plus potential on the R2 conductor strip 434 and A1B conductor strip 425 in the commutator switch 400, the DISC-TAX push button switch 900 being operated to close its upper contact against its lower contact. Plus potential will also be supplied on energizing point "8" in the bank 322 over conductor 811 to the circuit for the operation of the tab solenoid 305. In the tab motor circuit the carriage of the typewriter is automatically tabbed to the "total" column, the wiper contacts of the carriages in the commutator switch 400 completing the circuit between the R2 conducting strip 434 and the commutator segments associated therewith and the wiper contact 674, completing the circuit between the A1B conductor strip 425 and the segmental contacts associated therewith in the order of their arrangement. The carriage dials in the calculator 200, through the carriage dial switches associated therewith, operate to read out the accumulated total and the total is re-entered in the Add Keyboard of the calculator through the A1B conductor strip 425. The end segment 465 in the R2 conductor strip 434 section of the commutator switch 400 will energize the step relay 307(R₂) by way of conductors 837, 838 and 819, which, in turn, will operate to cause energization of the step switch coil 319. The pulsing point "8" in bank 324 of the step switch will apply energizing current over conductor 901 to the carriage return solenoid 800, which is in connection with conductor 804. The carriage return switch 339 is actuated to open the circuit between the step switch wipers and plus potential to operate the step switch to move to point "9."

Energizing point "9" in the bank 322 will apply plus potential over conductor 902 to the M2 conductor strip 431. The operator will manually tab to the column for entry of the percent of discount, or tax, which is entered in the Multiply Keyboard by selective operation of the solenoids 207. After entering the amount in the Multiply Keyboard, the tab is continued into the total column, at which point the step switch coil 319 is energized through the timing point "9" in the bank 321. Pulse point "9" in the bank 323 by way of conductors 875 and 874 and the hold switch 872 provides a holding circuit for the step switch coil 319. Pulse point "9" in the bank 324 operates by way of conductors 881 and 869 to apply plus potential to the Multiply Tab magnet 214, and through the Multiply Tab switch 884 and by way of conductors 870 and 871, plus potential is supplied to the multiply solenoid 665. The multiply cycle brings about operation of the holding switch 872 to open the step switch holding circuit to allow the step switch to move its wipers to step "10." At timing point "10" in the bank 321 the step switch is operated by way of conductors 737 and 738 as soon as the multiply cycle is completed to close the cycle switch 232. Pulse point "10" in the bank 323 will apply plus potential by way of conductors 903 and 889 to the right shift solenoid 222, which will start the right shift cycle in the calculator 200, also actuating the cycle switch 232 to open to remove the plus potential from timing point "10" to allow the step switch to move to point "11." Energizing point "11" will apply plus potential to the R1B conductor strip 433 and the A3 conductor strip 428. When the carriage of the typewriter moves to the total column, and the right shift cycle has completed, the right carriage dials in the calculator are read out and re-entered in the Add Keyboard. The end commutator segment 905, served by conductor strip R1B 433, will energize the step relay 307(R₂) which in turn, energizes the step switch coil 319. Pulsing point "11" in the bank 324 will energize

the plus or minus bus 894 and, in turn, the plus or minus solenoid is energized depending on whether the TAX button 906 or DISC button 907 is depressed. The add or subtract cycle actuates the cycle switch 232 to open the plus potential circuit to the step switch coil 319 from the end commutator segment 905 of the R1B section of the commutator switch so that the step switch wiper contacts move to point "12."

As soon as the add or subtract cycle has completed, 10 and the cycle switch 232 closes, the timing point "12" in the bank 321 will cause energization of the step switch coil 319, timing point "12" being connected to conductor 908 which is in electrical connection with conductor 888 leading from conductor 342. Pulsing point "12" in the 15 bank 324, when engaged by wiper contact 763, will put plus potential on conductors 909 and 901 to energize the carriage return solenoid 800 of the typewriter. The carriage return switch 339 opens the plus potential circuit to the timing wiper and point "12," and the step switch 20 moves to point "13."

The above program reads out the total and re-enters it to the Add Keyboard in the calculator. The operator enters the percentage of discount or tax and then tabs into the total column. The total and percentage are 25 multiplied together. The carriage of the calculator shifts right. The amount of tax or discount is read out and re-entered into the Add Keyboard. The amount of tax or discount is added to, or subtracted from, the accumulated total.

Plus and minus program

The plus and minus programs are the same except that in one the fixed amount is added to, and in the other it is subtracted from the accumulated total. The programs can be used to give a fixed credit and subtract it from the total, or to enter a fixed charge, such as packing or freight, and add it to the accumulated total.

Depressing the plus or minus program switches 910 and 911, respectively, will energize the home relay 306 40 (R₁) and position the wiper contacts of the step switch 318 to point "13"; the beginning of the plus and minus programs.

Energizing point "13" in the bank 322 will extend plus potential by way of conductors 912 and 913 to A3 conductor strip 428 by way of the cable 347. When the carriage is tabbed to the total column, the carriage wipers 677 complete the circuit between the A3 conductor strip 428 and the segmental contacts 465 and 458 to 464, inclusive, associated therewith, the segmental contacts being engaged in succession as the carriage bearing the wiper 45 contact 677 moves along conductor strip 428(A3). The fixed amount now printed in the total column will enter the Add Keyboard through the A3 conductor strip 428 section of the commutator switch 400, the segmental contacts 465 and 458 to 464, inclusive, being in electrical connection with the electromagnets in the Add Keyboard section of the calculator. The contact segment to the right of the contact segment 458, and which is the third commutator segment to the right of the decimal point position 914, will energize the step relay 307(R₂), which, 50 through its contacts, in turn, will energize the step switch 319. Pulse point "13" in the bank 323 will apply plus potential over conductors 915 and 889 to the right shift solenoid 222 for a right shift operation of the carriage 55 of the calculator 200. The right shift cycle of the calculator will cause the carriage to shift to the right and also actuate the cycle switch 232, which will open the plus potential circuit to the step relay 307(R₂) which will drop out and allow the step switch wiper contacts 60 to move to point "14."

At the end of the right shift cycle the cycle switch 232 closes again. The plus potential on timing point "14" in the bank 321 will be extended over conductors 908, 888, wiper contact 760, switch 761 and conductors 737 and 738 to the step switch coil 319 to pull the step switch 75 coil again as required to condition the switch for the next

one-step movement. Pulsing point "14" in the bank 324 will extend by way of conductors 916, 917 in the nonadd push button switch 792, will energize the plus or minus bus 894 and the plus solenoid 219 or the minus solenoid 220 in accordance with the condition of the add and subtract switches 916 and 917, respectively. The add or subtract cycle will actuate the cycle switch 232 to open the plus potential circuit to the timing wiper 760 allowing the wiper contacts of the step switch 318 to move to point "15."

After the add or subtract cycle has completed, the cycle switch 232 again closes, applying plus potential to the timing point "15" to pull the step switch again. Pulsing point "15" in the bank 323 operates to put plus potential on the step switch coil 319 by way of conductors 918, 897, 734, 735, rectifier 736 and conductors 737 and 738. Pulsing point "15" in the bank 323 also operates to put plus potential on the home relay 306(R₁) by way of conductors 918, 897, 734, 743, switch 744, and conductors 745 and 746. The home relay 306(R₁), in turn, through operation of its movable contact 336 to the lower position, energizes the carriage return solenoid 800 and automatically positions the step switch to the beginning of the plus or minus program.

The above program enters a fixed amount to the total column. After entering the second digit to the right of the decimal point, the program will automatically shift the carriage of the calculator to the right and then add to, or subtract from, the accumulated total the entered fixed amount.

COUNTER TOTAL PROGRAM: (QUANTITY COLUMN—R3 READOUT) (TOTAL COLUMN—R2 READOUT)

The counter total program is the readout of the counter dials and the accumulated total.

Depressing the counter total program push button switch 790 automatically cycles the step switch to point "16," the beginning of the counter total program.

Energizing point "16" will apply plus potential to the R3 conductor strip 435 and by way of the movable contact 716 in the counter switch 715, will apply plus potential by way of conductors 719 and contacts 720 and 721 of the MULT DEC Relay (R_{5-B}) to conductor 722 and MULT DEC Relay (R₅) if the counter total control switch is in the control total position. When the carriage enters the quantity column the counter dials will be read out through the R3 conductor strip 435 and the commutator segments 818 and 484 to 492, inclusive. The end commutator segment 818 will energize the step relay 307(R₂) by way of conductors 920, 838 and 819. The step relay 307(R₂) in operation, will, in turn cause energization of the step switch coil 319. Pulsing point "16" in the bank 323 will, by way of conductor 807, tab switch contacts 806 and conductor 808, cause energization of the tab solenoid 805. The tab cycle actuating tab switch 350 will open the minus potential circuit to the step relay 307(R₂), dropping it out, which, in turn, drops out the step switch coil 319 allowing the wiper contacts to move to point "17." Pulse point "16" in bank 324 will apply a positive potential to the MULT DEC relay 310(R₅) which tends to drop this relay out.

Energizing point "17" by way of conductor 921, will energize the R2 conductor strip 434, and by way of conductors 811 and 807, will energize the automatic tabbing circuit involving the tab relay 308(R₃) and the tab solenoid 805. As soon as the first tab cycle has completed, due to the tab solenoid 805 being energized from pulse point "16" in the bank 323, the typewriter carriage will automatically tab to the total column. The R2 conductor strip 434 and its associated segmental contacts 465 and 477 to 483, inclusive, which are brought into connection in succession by means of the wiper contact 681, will operate to read out the accumulated total. The end commutator segment 465 will energize the step relay 307(R₂) which pulls to energize the step switch coil 319.

Pulse point "17" in bank 323 will carry positive potential by way of conductor 922 to counter nonaccumulate magnet 223 setting the counter up to be cleared during the clear program. Pulse point "17" in the bank 324 will supply potential to energize the carriage return solenoid 800. The carriage return switch 339 opening the plus potential circuit to the step relay 307(R₂), contacts 839 will de-energize step switch coil 319, dropping it out and allowing the step switch to move to point "18."

10

Total and clear program

The total and clear program reads out the accumulated total in the left-hand dials of the calculating machine 200 and then clears the calculating machine.

15

Depressing the TOT CLR program push button 791 will operate to energize the home relay 306(R₁), and positions the step switch to point "19," the beginning of the total and clear program.

20

Energizing point "19," when the total program switch 923 is closed, applies plus potential by way of conductors 924 and 757 to the R2 conductor strip 434, the automatic tab circuit, and if the counter switch 925 is closed the M1B conductor strip 430 is also energized. The typewriter carriage automatically tabs to the total column

25

and the R2 conductor strip 434 and its associated segmental contacts 465 and 477 to 483, inclusive, reads out the accumulated total. If the counter dials are being used for control total, the readout is also entered into the Multiply Keyboard. The end commutator segment 465 of the R2 conductor strip portion 434 of the commutator switch 400 will energize the step relay 307(R₂) which, in turn, operates to supply the step switch coil 319 to pull the step switch in preparation for another step operation. Pulse point "19" in the bank

30

323 will energize the counter nonaccumulate magnet 223 if the counter dials are used for quantity total. If the counter dials are being used for control total, pulse point "19" in the bank 323 energizes the counter entry magnet 217, since, under this condition, the counter switch and movable contact 926 will be in contact with fixed contact 927 to provide plus potential over conductors 928 and 840 for the operation of counter entry magnet 217. When the movable contact 926 of the counter switch is in contact with fixed contact 929, the potential is supplied to counter nonaccumulate magnet 223 by way of conductors 930 and 922. Pulse point "19" in the bank 324 energizes over conductors 909 and 901, the carriage return solenoid 800, the circuit being continued from carriage return solenoid 800 by way of conductor 804, tab switch 350, conductor 354, shift lock switch 351, conductor 352 to conductor 353. The carriage return switch 339 is actuated to open the plus potential circuit leading to the step relay 307(R₂) to cause the relay to drop out which, in turn, allows the step switch to move

35

to point "20."

40

At the completion of the carriage return cycle, plus potential is applied to timing point "20" in the bank 321 to supply energy over the conductors 908, 921, wiper contact 760 and switch 761, conductor 932, conductors 737 and 738 to pull the step switch coil 319. Pulse point "20" in the bank 323 applies potential over conductor 933 to operate left-hand carriage nonaccumulate magnet 224 to remove the split condition of the calculator carriage at the point "934." Pulse point "20" in the bank 324 energizes the multiply solenoid 208 over conductors 935 and 871, therefore, if the accumulated total is in the Multiply Keyboard, it is transferred to the counter dials in the calculator. The multiply cycle actuates cycle switch 232 in the calculator to remove the plus potential from the timing point "20" in the bank 321 allowing the step switch to operate to move its wiper contacts to point "21."

45

At the end of the multiply cycle, the cycle switch of the calculator is closed to apply plus potential to timing point "21," which is in electrical connection with con-

50

60

65

70

75

ductor 908 through conductor 936 and the step switch is pulled ready for another step movement. Pulse point "21" in the bank 324 energizes the counter nonentry magnet 218 by way of conductors 937 and 891. Pulse point "21" in the bank 323 energizes, by way of conductors 938 and 939, 780 and 779, the restore relay 312(R₇), which operates through the switch 769(R₇) contacts to close the circuit for the restore magnets 770 and 771 which are operable to restore the selecting slides and the armatures of electromagnetic devices in the calculator to normal positions and, in effect, clear the calculator keyboard, the carriage dials and the counter dials if the counter is being used for quantity total. The cycle switch 232 operates to open the circuit for the step switch and the wiper contacts move to point "22." On pulsing point "22" the dividend entry solenoid 221 in the calculator is energized over conductor 940. The dividend entry cycle actuates the cycle switch 232 and the step switch operates to permit its wiper contacts to move to the point "23" position.

After the dividend entry cycle, the cycle switch operates in succession and the step switch wipers are moved in steps across point "23" and to point "24." On timing point "24" plus potential is supplied from conductor 941 to pull the step switch for the next step movement. On pulsing point "24" in bank 323 plus potential is provided by way of conductor 942 to operate the multiply clear solenoid 209. On the pulsing point "24" in the bank 324 plus potential is supplied over conductors 943 and 891 to operate counter nonentry magnet 218. The cycle switch 232 operates to open the circuit of the step switch coil 319 and the step switch wipers move to point "25." On timing point "25" plus potential is supplied by way of conductor 944 to energize the step switch coil 319. On pulsing point "25" in the bank 323 plus potential is supplied by way of conductors 945 and 940 to operate dividend entry solenoid 221. After the dividend entry cycle the cycle switch 232 opens to permit the step switch to move its wiper contacts to the number "26" position.

In the number "26" position in the timing bank 321 the number "26" point contact is supplied with positive potential over conductor 946 to operate the step switch coil 319 by way of the wiper contact 760, switch 761 of the home relay 306(R_{1-D}), conductors 932, 737 and 738. Point "26" in the pulsing bank 323 plus potential is provided over conductors 947, 897, 734, 743, contacts 744, conductors 745 and 746 to operate the home relay 306(R₁). On pulsing point "26" in bank 324 plus potential is supplied by way of conductor 948 to operate the ERR push button release magnet 225.

Error program

The error program is used to clear the Multiply Keyboard, Add Keyboard and the right-hand carriage of the calculator 200.

Depressing the ERR push button to bring the movable contact 948 across the fixed contacts 949 and 950, energizes the home relay 306(R₁) over a circuit extending from conductor 759 to fixed contact 949, movable contact 948, fixed contact 950, conductor 951, conductor 743, contacts 744, conductor 745, conductor 746, and positions the step switch wiper contacts to point "24" for the beginning of the error program. In operating the ERR push button 952 the movable contact 948 is momentarily moved across the fixed contacts 949 and 950, but the movable contact 953 is latched against contact 954. Depressing any of the other program push buttons would release those already held in, but the ERR push button 952 has its own latch with a magnet release, therefore, at the end of a cycle for the error program the step switch automatically cycles to the beginning of the program where the error was made.

Timing point "24" has plus potential on it so the step switch coil 319 pulls in preparation for the next step

movement. Pulsing point "24" in the bank 323 provides plus potential over conductor 942 to energize the multiply clear solenoid 209. Pulsing point "24" in the bank 324 supplies plus potential over conductors 943 and 891 to the counter nonentry magnet 218. The multiply cycle actuates the cycle switch 232 to break the energizing circuit to allow the step switch 318 to move its wiper contacts to point "25."

At the end of the multiply cycle the cycle switch 232 closes to apply plus potential to timing point "25," to pull the step switch, again pulsing point "25" in the bank 323 energizing the dividend entry solenoid 221, which clears the right-hand carriage of the calculator and clears the Add Keyboard. The dividend entry cycle actuates the cycle switch 232 to de-energize the step switch coil 319 and allow the step switch to move its wiper contacts to point "26."

At the end of the dividend entry cycle the cycle switch 232 closes, applying plus potential to timing point "26" 20 by way of conductors 908 and 946 to pull up the step switch coil 319 ready for another step operation. Pulse point "26" in the bank 323 supplies plus potential over conductors 947, 951, 743, contact 744 and conductors 745 and 746 to energize the home relay 306(R₁) to start 25 cycling of the step switch coil 319 to bring the step switch wipers to the bank contacts at the beginning of the program in which the error was made. Pulse point "26" in the bank 324 supplies plus potential over conductor 948 to the ERR push button release magnet 225 to release 30 the contact 953 from latched engagement with the contact 954. An error in the program can be cleared if the accumulated total has not been calculated.

Nonadd program

The NON ADD program push button 792 can be used when it is desired to proceed with a program but not affect the accumulated total. After a program button is depressed, the NON ADD push button 792 can be depressed which has a separate mechanical lock and magnet release. The positive potential from the pulsing points "6," "11" and "14" in the bank 324 to the plus and minus bus 894 is transferred by the nonadd contacts and the NON ADD push button 792 to energize the restore relay 312(R₇). This provides a releasing pair of contacts 341 in series with the cycle switch 232 in the calculator, but the amount read out and entered into the Add Keyboard will not affect the accumulated total. If the NON ADD push button is depressed, the next time the home relay 306(R₁) is energized, this plus potential 50 also energizes the nonadd release magnet 795 to release the NOW ADD push button 792.

What is claimed is:

1. In a combination of a typewriter and calculating machine in which amounts are stored in column positioned registers and are read out of the registers for typing the amounts in corresponding columns in a sheet, a carriage in the typewriter, a commutator switch in the typewriter comprising a first set of conductor strips supported in parallel spaced relation, a second set of conductor strips extending in spaced relation with and crosswise of said first set of conductor strips, a switch carrying carriage operable lengthwise of one of said sets of conductor strips and crosswise of the other set of conductor strips, wiper contact means carried by said switch carrying carriage and operable to form electrical connecting means between the first set of conductor strips and the second set of conductor strips and carriage operating means carried by the carriage of the typewriter and operable to move the switch carrying carriage in said commutator switch.
2. In a combination of a typewriter and calculating machine in which amounts are calculated and stored in column positioned registers and are read out of the registers for typing the amounts in corresponding columns in a sheet, a commutator switch in the typewriter comprising

a first set of conductor strips supported in parallel spaced relation, a second set of conductor strips extending in spaced relation with and crosswise of said first set of conductor strips, a set of contact carrying carriages and wiper contacts carried thereby in frictional contact with said sets of conductor strips, a carriage in said typewriter and means carried on the carriage of said typewriter and operable to engage and move said set of contact carrying carriages during the movements of the typewriter carriage.

3. In a typewriter operable to control electrical apparatus, a carriage in the typewriter, an electrical commutator switch, movable contact carrying carriages in said commutator switch and releasable latch means on said contact carrying carriages in said commutator switch and on said carriage in the typewriter to releasably latch the carriage in said typewriter to said contact carrying carriages in said commutator switch.

4. In a combination of a typewriter and calculating machine in which amounts are entered in the calculator through operation of the typewriter, a carriage in said typewriter, an electrical commutator switch in said typewriter forming an electrical control means between said typewriter and calculating machine, contact carrying carriages in said commutator switch, movable contacts of said commutator switch carried by said contact carrying carriages and latch means on said contact carrying carriages and on the carriage of said typewriter to releasably latch the carriage of the typewriter to said contact carrying carriages in said commutator switch.

5. In a machine operable to control electrical apparatus, a commutator switch, a contact carrying carriage supporting movable contacts in said commutator switch, latch fingers supported on said contact carrying carriage and cooperable to accommodate a movable member, a carriage in said machine and a bar carried by the carriage in said machine and operable to find accommodation between and in engagement with said latch fingers when the carriage in said machine is moved relative to said commutator switch.

6. In a combination of a typewriter and calculator machine in which amounts are entered in the calculator through operation of the typewriter, an electrical commutator switch in said typewriter forming an electrical control means from said typewriter to said calculator machine and from said calculator machine to said typewriter, contact carrying carriage means and movable contacts carried thereby in said commutator switch, latch means on said contact carrying carriage means, a carriage in said typewriter and latch engageable means on the typewriter carriage to permit releasable latching of said contact carrying carriage means to the carriage of said typewriter.

7. In a machine, operable to control electrical apparatus, a carriage, a commutator switch, contact carrying carriages supporting movable contacts in said commutator switch, releasable latch members on the contact carrying carriages in said commutator switch and latch engaging means carried by said carriage and operable upon movement of said carriage to engage and move said contact carrying carriages in said commutator switch.

8. In a machine operable to control electrical apparatus, a commutator switch, conductor strips supported in said commutator switch, contact carrying carriages supporting movable contacts in engagement with said conductor strips, spring-biased latch fingers on said contact carrying carriages and a movable bar operable to engage said latch fingers and move said contact carrying carriages along said conductor strips.

9. In a calculating and recording apparatus comprising a body and a relatively movable carriage, a switch comprising sets of conductor strips, a set of contact carrying carriages carrying wiper contacts into and out of contact with said sets of conductor strips, releasable latch means on said set of contact carrying carriages,

bar means carried on said movable carriage and operable to engage said latch means and serve in cooperation therewith to couple said relatively movable carriage to said set of contact carrying carriages and ramp means to release said latch means from said bar means.

10. In a calculating and recording apparatus comprising a carriage, a switch, a fixed support for said switch, contact carrying carriages movably supported in said switch and carrying movable contacts of said switch, latch means on the contact carrying carriages in said switch, bar means carried by said carriage and engageable with said latch means to move said contact carrying carriages in excursions across said switch and ramp means in the paths of movement of said contact carrying carriages and operable to release said latch means from said bar means.

11. In a typewriter arranged to control exterior apparatus in accordance with operations of the typewriter, a carriage, a switch supported by said typewriter, contact supporting plates of insulating material supported in spaced relation in said switch, conductor strips forming the contacts on said contact supporting plates, the conductor strips on one contact supporting plate being arranged crosswise relative to the conductor strips on another of said contact supporting plates, a set of contact carrying carriages carrying wiper contacts into and out of contact with said conductor strips and operable back and forth across said contact supporting plates, latch fingers on said set of contact carrying carriages, bars carried by said carriage of the typewriter and arranged for latching engagement with said latch fingers and splay strips extending across the paths of movement of said contact carrying carriages in said switch and operable to cam said latch fingers out of latched engagement with said bars.

12. In an office machine, operable to control electrical apparatus, a commutator switch, a first set of conductor strips supported in said commutator switch, a second set of conductor strips spaced from and extending crosswise relative to said first set, contact carrying carriages extending between said first and second set of conductor strips, contacts carried on said contact carrying carriages and operable to form electrical conductor paths from the conductor strips in said first set to conductor strips in said second set, paired spring-biased latch fingers on said contact carrying carriages, each pair of latch fingers being cooperable to receive between them an operating member, a carriage in said office machine, a bar carried by the carriage in said office machine and operable to engage said latch fingers and move said contact carrying carriages and ramps on said commutator switch engageable by said latch fingers and operable to release said latch fingers from engagement with said bar.

13. In a typewriter arranged to control exterior apparatus in accordance with operations of the typewriter, a carriage, a switch comprising a first set of conductor strips, a second set of conductor strips arranged in spaced relation with and crosswise with respect to said first set of conductor strips, a set of contact carrying carriages carrying movable contacts of said switch into and out of contact with said conductor strips, spring-biased latch fingers on said set of contact carrying carriages, a movable member carried on the carriage of said typewriter and operable to pass into and out of contact with said latch fingers and to be caught by said latch fingers and ramp bars in the path of movement of said contact carrying carriages in said switch to cam said latch fingers out of holding engagement with said movable member.

14. A calculator and recorder apparatus comprising, in combination, a typewriter, a calculator, a control unit having electrical connection with said typewriter and calculator and providing means through which said typewriter may control the operations of said calculator.

tor and said calculator may control the operations of said typewriter, a step switch in said control unit operable to control the operations of said control unit in predetermined steps, a set of keys in circuit connection with said step switch and operable to control and selectively set the pattern of operation of said step switch and a commutator switch in said typewriter, comprising a plurality of sets of spaced fixed contacts and movable contacts on reciprocating contact carrying carriages and operable in combination with said step switch to control 10 said typewriter to type, in predetermined column positions on a record sheet, the values calculated in said calculator.
